UNITED STATES PATENT OFFICE.

HARRY WALKER, OF OIL CITY, LOUISIANA, ASSIGNOR, BY DIRECT AND MESNE ASSIGNMENTS, TO NATIONAL MANUFACTURING COMPANY OF AMERICA, OF OIL CITY, LOUISIANA, A CORPORATION OF DELAWARE.

AUTOMATIC AND COIN-CONTROLLED MULTIPLE PHONOGRAPH.

Application filed November 27, 1925. Serial No. 71,817.

The present invention appertains to that class of phonographs or talking machines which are adapted to play a plurality of disc records successively and selectively, or 5 in any desired order.

An important object of the invention is to provide a simple, economical, and efficient phonograph or machine for reproducing sounds, adapted to enable a plurality of records to be played in successive order, or selectively.

Another important object of the invention is to provide in a phonograph or a machine for reproducing sounds, a simple and efficient means for automatically placing, one at a time, a plurality of records upon a turn table or rotative record support in successive order, and removing them from the turn table successively, in such a manner as to 15 enable any desired one or more of a plurality of records to be successively played and returned to position to be readily accessible for further and repeated use.

Another important object of the invention 25 is to provide a phonograph which is automatic in its operation in that it is only necessary to push an operating switch manually or to drop a coin in a coin controlled switch mechanism whereby a disc record is removed 30 from a vertically movable magazine, placed upon a rotating turn table, after which the reproducing stylus is caused to engage the record for the purpose of playing the same. After the record has been played, the stylus 35 is lifted out of playing engagement with the same, and the record is removed from the turn table and replaced in its proper place in the magazine, thereafter the turn table is stopped automatically or allowed to continue 40 in operation if it is desired to play a second, a third, etc. record, all parts being automatically operated to carry out their functions in proper order.

The machine of the present invention also 45 contemplates the reproduction, when desired, of any given record among a plurality of different records carried in a shiftable magazine which is both automatically and manually controlled.

50 In carrying out this invention, a mechanism has been provided in which the various parts for carrying out one step in the cycle are so inter-related and constructed as to form the actuating means for setting in op-

eration or for actually operating the mechanism for performing the next step in the cycle of operation. In this manner a unitary machine is provided in which only comparatively few elements are necessary in view of the several functions accomplished, 60 and in which all unnecessary elements are eliminated.

In the present embodiment of the invention any number of disc records of various sizes may be used, and the apparatus automatically operated regardless of the length 65 of each record played. The embodiment of the invention which I have disclosed merely by way of example includes the use of a suitable motor for operating the mechanism 70 for reproducing the sound and for operating the record shifting mechanism and movable magazine for selecting the records, said mechanism being so controlled by a unitary controlling mechanism that when the machine has finished the reproduction of one record, said record is returned to the magazine 75 and another record placed in operative position for reproduction and the stylus engaged therewith. This operation may be 80 carried on continuously, the set of records in the magazine being played in a regular order, or the machine may be operated to carry out only a single cycle, namely to place a record in engagement with the reproduction 85 means and return it to the magazine after having been played.

The operation of the entire mechanism is automatic throughout, and one cycle of operation may be summarized as follows:

In normal position all of the records are 90 located within the magazine, and the apparatus may be started by manual operation of a switch, or by placing a coin in a coin controlled circuit closer. A record is first 95 transferred from the magazine to the turn table by a carrier or shifter arm. The turn table is in operation as soon as one of the aforementioned switches has been closed. As the record is being positioned upon the 100 turn table of the sound reproducing mechanism, the shifter arm operates to return the reproducer and sound box which has been raised and left above the record at the end of the groove in the same, to the periphery 105 of the turn table, or the initial starting position. As the record is lowered on the turn table, the sound box is automatically low-

ered onto the record and the actual reproduction starts. After the reproducer reaches the end of the record, and stops its inwardly directed movement, suitable clutch actuating mechanism is placed in operation for effecting the mechanism which raises the sound box from the record and actuates the shifter arm to return the record played to its initial position in the magazine. This shifter arm 10 controls, if desired, a switch which will stop the operating motor after the record has been returned to the magazine. If another cycle is started, the record magazine is first automatically shifted so that another record 15 will be selected by the shifter arm for reproduction.

It is apparent that many forms of mechanism may be provided for carrying out the object of the present invention, and I have shown one means for accomplishing each of the steps forming a part of this invention. The mechanism shown for carrying out each operation, however, is merely shown for the purpose of illustration and said particular 20 form of mechanism has been selected for illustration since the same has proved in actual practice to be both efficient and reliable. Changes in the details of construction, and in the combination and arrangement of parts may be resorted to without departing from the spirit or scope of the invention as hereinafter described and claimed.

In the drawings:

35 Figure 1 is a front elevation of the sound reproducing apparatus embodying the features of my invention showing a portion of the dust proof screen broken away.

Figure 2 is a top plan view of the apparatus with the cover of the cabinet removed.

40 Figure 3 is a vertical section taken through the apparatus substantially on the line 3—3 of Figure 2 showing particularly the record magazine and counter balance mechanism associated therewith.

45 Figure 4 is another vertical section taken through the apparatus substantially on the line 4—4 of Figure 2.

Figure 5 is a fragmentary top plan view 50 of the mechanism producing the steps in the operation of the apparatus, the turn table being removed and certain parts being shown in section.

55 Figure 6 is an enlarged detail section taken substantially on the line 6—6 of Figure 5, showing the catch engaged with the rod of the clutch operating mechanism.

Figure 7 is a view similar to Figure 6 showing the catch disengaged,

60 Figure 8 is a detail perspective of the catch and its operating foot,

Figures 9 and 10 are diagrammatic plan views of the clutch operating mechanism,

65 Figure 11 is an enlarged detail section through the center portion of the turn table

with a record thereon taken substantially on line 11—11 of Fig. 2.

Figure 12 is an enlarged fragmentary vertical section taken substantially on the line 12—12 of Figure 2.

70 Figure 13 is an enlarged detail fragmentary section taken on the line 13—13 of Figure 5,

Figure 14 is a top plan view of the mechanism shown in Figure 13.

75 Figure 15 is a view similar to Figure 14, with the parts in a different position.

Figure 16 is a detail perspective view of the clutch tensioning lever,

80 Figure 17 is an enlarged detail sectional elevation taken substantially on the line 17—17 of Figure 14,

Figure 18 is an enlarged detail perspective view of a catch and lift lever for the rod of the clutch operating mechanism,

85 Figure 19 is an enlarged detail fragmentary section taken substantially on the line 19—19 of Figure 5,

90 Figure 20 is an enlarged fragmentary detail section taken substantially on the line 19—19 of Figure 5, looking in an opposite direction to the view shown in Figure 19,

Figure 21 is an enlarged fragmentary elevation of the record magazine,

95 Figure 22 is an enlarged fragmentary bottom plan view of the record magazine,

Figure 23 is an enlarged detail fragmentary section taken substantially on the line 23—23 of Figure 5, showing particularly the escapement mechanism.

100 Figure 24 is an enlarged fragmentary sectional elevation taken substantially on the line 24—24 of Figure 5, parts not being shown for clearness,

Figure 25 is an enlarged fragmentary diagrammatic view in plan showing the shifter arm carrying a record,

105 Figure 26 is a longitudinal section, partly in elevation, of the shifter arm,

Figure 27 is a bottom plan view of the shifter arm.

Figure 28 is a section taken on the line 28—28 of Figure 26,

110 Figure 29 is an enlarged fragmentary detail sectional elevation taken substantially on the line 29—29 of Figure 19,

Figure 30 is a detail perspective view of the rod of the clutch operating mechanism,

115 Figures 31, 32, and 33 are detail sectional views taken substantially on the lines 31—31, 32—32, and 33—33 respectively of Figure 24,

Figure 34 is a detail section taken substantially on the line 34—34 of Figure 5,

120 Figure 35 is a detail perspective view of the key for operating the damper,

Figure 36 is a diagrammatic view of the circuit used in the control of this apparatus, and

125 Figure 37 is a detail sectional view show-

ing the shifter arm supported by a bell crank lever in its raised position.

Referring particularly to Figures 1 to 4 inclusive, it will be seen that my cabinet construction is illustrated to advantage. The numeral 5 represents the bottom which rests on supporting elements 6. Rising from the bottom 5 are the rear wall 7, the side wall 8, the side wall 9, and the front wall 10. A cover 11 preferably having transparent members 12 therein is hinged as at 13 to the upper edge of the rear wall 7. An electric incandescent light bulb 14 is mounted in a socket 15 suitably suspended from the top of the cover for the purpose of illuminating the interior of the cabinet when the reproducer is in operation. The front wall 10 is provided with an opening 16. The bottom edge of the opening 16 is provided with a longitudinally extending groove 17, while the upper edge thereof is provided with a similar groove 18. A dust proof screen 19 is removably mounted in the opening 16, the upper edge thereof being first inserted in the groove 18, so that the lower edge thereof may be rested in the groove 17. The outer end of a horn 20 is flared and registered with the major portion of the opening 16. The horn 20 extends rearwardly from the opening 16, and is then curved laterally and is further curved to extend forwardly and upwardly for communicating with the socket bracket 21 of the tone arm 22. A conventional sound box 23 is mounted on the free end of the tone arm 22 for playing disc records placed on the turn table 24, which will be referred to more in detail later in the description. Suitable cleats 26 are mounted on the four walls of the cabinet for supporting a rectangular frame 27 adjacent the upper edges of said walls. An electric motor 28 is suspended from a cross bar 29 of the frame 27, and the armature shaft thereof has a grooved pulley 30, over which is trained a belt 31. A speed governor 32 is mounted in the governor frame 33 suspended from the frame 27 and the belt 31 is trained over the pulley 34 thereof. The governor shaft has an operative connection 35 with a vertical spindle 36 suitably journaled in the frame 33 to project slightly above the frame 27 for receiving at its upper end the hub 38 of the turn table 24. The hub is provided with a notch 39 for receiving a laterally disposed pin 40 projecting from the spindle 36, so that the turn table will be revolved upon the rotation of the spindle 36 from the motor through the governor. A centering pin 41 rises from the upper end of the spindle 36. Each record 42 is of the disc type, being provided with the usual central aperture 43. In each aperture 43 there is disposed a carrier button as is indicated to advantage in Figure 11 and indicated generally by the numeral 44. Each

carrier button includes a hollow body adapted to pierce the aperture 43 of its record and to be received on the centering pin 41. An outwardly disposed annular flange 46 is provided on the bottom end of the body 45 while the upper end of said body terminates in a reduced neck 47, the upper end of which is provided with a head. The further purpose of these carrier buttons will appear later in the description. 75

The frame 27 is provided with bracket arms 48 and 49 projecting rearwardly from the front rail thereof, as may be more clearly seen in Figure 5. The socket 21 for the tone arm 22 is mounted on an intermediate portion of the bracket arm 49, and bracket arms 50 which project inwardly from one side rail of the frame 27. A journal bracket 52 depends from the bracket arm 48. A bracket structure 53 depends from the bracket arm 49, and is provided with a bearing 54. A main shaft 55 is journaled in bearing 52 and bearing 54. Particular attention is now directed to Figures 13 to 17 inclusive wherein it will be seen that numeral 56 designates a manually operated shaft extending through the side wall 8 of the cabinet and having an operating knob 57 on its outer end. This shaft 56 is journaled in a bracket 58 (see Figure 2) supported by one side rail of the frame 27 and is formed in sections held together by a coupling 59 fixed on the main section and engageable with the auxiliary section by a set screw 60. A main drive gear 61 is fixed 100 on the main shaft 55 for driving the latter as will be explained later. A disc portion 62 is provided with a hub 63 fixed to the shaft 55 by a screw 64 or in any other suitable manner. The shaft 56 terminates in a 105 portion of the hub 63. A ratchet clutch face 65 is provided on the hub 63 for engagement with the ratchet clutch face 66 on one side of a hub 67 rotatable and slideable on the shaft 56. A ratchet clutch segment 68 is 110 splined as at 69 on the shaft 56 for engaging the other ratchet clutch face 70 of the hub 67. A spring 71 is disposed within the segment 68 and impinges against a shoulder 72 in said segment and against the inner portion 73 of the hub 67 for normally holding said hub 67 in an engageable position by the ratchet clutch face 65 of the hub 63. The segment 68 is provided with an annular groove 74. A tensioning lever 76 is 115 pivoted at one end on a pivot pin 75 mounted in a bracket 77 forming a part of bracket arm 48. Adjacent the free end of the lever 76 there is provided an upwardly curved portion 78, adjacent which and below which is disposed a projection 79 for being received in the groove 74. The free end of the lever 76 is disposed laterally and terminates in a downwardly disposed terminal 81. A hook 82 is provided on the laterally 120

125 130

disposed end 80 and is engaged by a spring 83 which is attached to a pendant 84 on the inner end of the bracket arm 48, so that the clutch segment 68 is normally maintained in an engageable position with the ratchet clutch face 70 of the collar 67, and also that proper tension is given the spring 71 to maintain the clutch face 66 of the collar 67 in an engageable position with the clutch face 65 of the hub 63. The spring 83 also holds the terminal of the end 80 in the space afforded by the ends 85 and 86 of the disc fragment 87. The end 86 is beveled for engaging the terminal 81 so as to swing the lever 76 to a position for maintaining the clutch segment 68 in an inactive position. A crank 88 extends radially from the hub 67 and has a roller 89 journaled on its free end. A counter shaft 90 is journaled in the depending portion 91 of the bracket arm 48 and has fixed thereto a star wheel 92 and a heart shaped cam 93, (see Figure 20), which is provided with a plurality of cam faces. At each revolution of either the main shaft 55 or the manually operated shaft 56 it will be seen that the crank 88 will be swung so that its roller engages the teeth of the star wheel 92 for rotating the shaft 90 to make active the cam faces of the heart shaped cam 93 in succession. A lift lever 94 (see Figure 20) is pivoted on the pin 75, and extends rearwardly for the purpose of shifting a record magazine which will be referred to later.

An intermediate portion 95 of the lever 94 rests on the outer periphery of the heart shaped cam 93, while a pin 96 supported by an arm 97 on the lever 94 engages the inner periphery thereof. Thus as the heart shaped cam revolves, an up and down stepped movement is imparted to the lift lever 94. A dog arm 98 (see Figs. 13 and 15) is pivoted on the pin 75 and has a roller 99 journaled on its free end for engaging between the teeth of the star wheel 92 to maintain it in the different positions to which it has been actuated by the crank 88.

For an understanding of the record magazine, attention is directed to Figures 3, 21, and 22. A pair of vertically extending, parallel, and spaced polished rods 100 extend through bracket sleeves 101 mounted on the rear rail of the frame 27. These polished rods 100 extend above and below the frame 27. The bottom 102 extends forwardly from a vertically disposed frame structure 103 having bearings 104 at the top and bottom thereof for sliding on the polish rods 100. A plurality of horizontally inclined shelves 105 are supported on the frame 103 above the bottom 102. These shelves 105 are vertically spaced and inclined downwardly and rearwardly. A bracket arm 107 depends from one rear corner of the frame 27. A V-shaped counter-balance lever 108 has one end pivoted as at 109 to the lower end of the bracket arm 107. The other end of the counter balance lever 108 is off set to form the extension 110, on the terminal of which is journaled a grooved wheel 111, for riding on a track bar 112 fixed to the bottom 102. A pair of hooks 113 and 114 are mounted on the pivoted arm of the counter balance lever 108 in spaced relation to each other. A bracket 115 is supported on the rear rail of the frame 27 and springs 116 and 117 are suspended thereto and attached respectively to hooks 113, and 114. These springs 116 and 117 cause the lever 108 to approximately counterbalance the magazine and the records supported therein. A program panel 118 is attached to the bracket member 115 so that a program may be placed thereon and may be visible through the transparent members 12 of the cover 11.

A vertically disposed shield 119 has a lateral portion 120 which is mounted on the rear rail of the frame 27. The shield 119 has an intermediately disposed opening 121 through which the numerals on the strips 122 may be seen as they are brought into registry with said opening. This strip 122 is provided with a pair of lateral extensions 123 which are attached to the frame 103, so that as the magazine is moved up and down, the numeral indicative of the record in the playing position will be registered with the opening 121. The end of the lift lever 94 has thereon a headed bolt 125 which is slidably engaged with the bottom 102, the head being held in engagement therewith by plates 126. It will therefore be seen that as the lever 94 is swung by the means heretofore described the magazine and the records therein are raised or lowered for the purpose of placing one of the records in a position so that it may be shifted to the turn table, as will be indicated later. The shelf holding the record to be shifted to the turn table is disposed substantially coplanar with the turn table.

Particular attention is now directed to the mechanism for shifting a record from the magazine to the turn table and restoring said record to the magazine after having been played, said mechanism being illustrated to advantage in Figures 5, 24 to 28 inclusive, and 31 and 32. The main shaft 55 has mounted on its end a disc 127, the hub 128 thereof having a set screw 129 for fixing this disc onto said shaft 55 so as to rotate therewith, and at the periphery of the disc 127 there is disposed an arcuate series of beveled gear teeth 130 which I shall refer to as the outer series, an inner series of beveled gear teeth 31 being provided in an arcuate arrangement on the disc between the periphery thereof and the hub 128 and opposed diametrically to the series 130. A vertical shaft 132 is journaled in the bracket 133 adjacent the disc 127 extending diametri-

cally thereof. Adjacent the bottom of this shaft 132 there is disposed a mutilated gear 133 having a gear segment 134 meshable with the inner series of teeth 131. Adjacent the upper end of the shaft 132 there is fixed thereto a second mutilated gear 135, having a gear segment 136 meshable with the outer series of teeth 130. The mutilated gears 133 and 135 are disposed so that their gear segments 134 and 136 respectively are disposed in substantially the same part of a circle described about the axis of the shaft 132. A head 138 is formed on the upper end of the shaft 132, and has flattened portions 139 diametrically opposed to each other. A shifter arm 141 has one end provided with a pair of space apertured ears 142 for straddling the head 138 so that each will be disposed adjacent one flat portion 139, screws 143 pivoting these ears to the flat portions 139 of the head 138. Thus the shifter arm 141 is pivotally mounted on the end of the shaft 132. The arm 141 is offset as at 144. The free end of the arm is provided with an L-shaped slot 145, having an outwardly flared entrance end 146. A bar 147 is slideable on the bottom face of the shifter arm 141 by means of screws 148 and the headed element 149 which depend from the arm 141. The outer end of the bar is notched as at 150, for registering with the entrance portion 146 of the L-shaped slot 145. As the shifter arm swings over a record in the magazine as will be explained later, the neck 47 of the carrier button 44 engages in the notch 150. When the bar 147 is slid outwardly of the arm 141 in a manner which will be explained later it will be seen that the neck of the button is locked in engagement with the innermost recess of the slot 145. An arcuate bracket 152 is mounted by a member 158 on the bracket arm 49 concentrically in relation to the shaft 132 and has thereon an arcuate rail 153 and an arcuate rail 154. The arc of the rail 153 is smaller than the arc of the rail 154. Both of these rails, however, are concentric in relation to the shaft 132. These rails are circumferentially spaced as is indicated to advantage in Figure 25, and the adjacent ends thereof are curved laterally in opposite directions, said end of the rail 153 being curved outwardly and said end of the rail 154 being curved inwardly as is indicated at 157, and 156 respectively. The inner end of the bar 147 is offset as at 159 for engaging the rails 153 and 154. As the arm 141 swings from its initial position indicated in Figure 5 it engages a carrier button as previously indicated, and then the offset end 159 engages the off set end 152 to ride on the outside of the rail 154, thereby pushing the rod 147 outwardly to lock the button in engagement with the arm as previously indicated. As the arm returns to its initial position, the offset end 159 engages the end 157 so as to cause the offset end 159 to ride on the inside of the rail 153, thereby moving the bar 147 inwardly to allow the disengagement of the shifter arm from the record carrier button. 70

An arcuate track 160 is supported on the member 158 concentric with the bracket 152 and inside thereof. An intermediate portion of this track is inclined upwardly as may be seen, for instance, in Figure 24. In 75 the raised portion of the track 160 there is provided a detent or recess 161 (see Fig. 5). An adjustable foot 168 in the form of a threaded member pierces the arm 141 so that its lower end is adapted to ride on the track 160. A hook 163 is provided on the arm 141 adjacent the foot 168, and a similar hook 164 is provided on the head 138 so that a spring 165 (see Figure 24) may be engaged therewith for holding the arm 80 downwardly with the foot 168 in engagement with the track 160. A screw threaded member 166 is engaged with the arm 141 to depend therefrom adjacent the foot 168 for the purpose of being engaged by lifting 85 means, referred to later.

As the description has thus far progressed, relative to the shifting mechanism it will be seen that when the main shaft 55 is placed in rotation, the disc 127 will be placed in 90 rotation therewith so that as the inner series of teeth 131 engage the gear segment 134 of the mutilated gear 133 the shifter arm will be moved from its initial position shown in Figure 2, first to a position shown in 95 Figure 25 for gripping and clamping the carrier button of the record on the shelf of the magazine located within the throw of the lever. As the shifter arm continues to swing toward the turn table it will be raised 100 by the foot 168 engaging the inclined portion of the track 160. Continued movement of the shifter arm will cause the foot 168 to be brought over the recess 161 so that the foot 168 will drop thereinto, thereby causing 105 the free end of the shifter arm to be lowered for depositing the record on the turn table with its carrier button engaged over the centering pin 41 of the spindle 36. As soon as the record is deposited on the turn table, 110 the gear segment 134 will have moved out of mesh with the inner series of gear teeth 131. As will be explained later at this point in the operation of the mechanism the main shaft will be stopped. After the record has 115 been played and the main shaft is again placed in operation as will be explained later, it will be seen that the outer series of gear teeth 130 of the disc 127 will be brought into mesh with the gear segment 125 136 of the mutilated gear 135 to rotate the shaft 132 in an opposite direction from that previously indicated so that the shifter arm may be returned to its initial position during 130 which operation it will replace the record

on the shelf from which it was taken. Immediately before the teeth 130 mesh with the teeth 136, the shifter arm is raised to lift the foot 168 out of the recess 161 as 5 will be explained later.

Referring now in detail to the means for placing the sound box in and out of engagement with the record on the turn table and the means for lifting the shifter arm to raise the record from the turn table as illustrated to advantage in Figures 19 and 23, it will be seen that a cam 165 is fixed to the main shaft 55 to rotate therewith. A lever 166 is pivoted at one end on the pin 75, and a spring 167 normally holds the lever raised with its free end in engagement with the cam 165. As this cam 165 rotates, it actuates the lever 166 downwardly. An arm 168 rises from the lever 166 and has a lateral extensions 169. A bell crank 170 (see Fig. 19) has one end resting on the extension 169 and the other end adapted to engage with the screw threaded member 166' of the shifter arm 141 as is shown in Fig. 37. When the spring 167 is holding the lever 166 in its normal raised position the upper end 171 of the bell crank 170 is in its raised position. The record is lowered on the turn table, by the cam 165 lowering the lever 166 so that the end 171 of the bell crank 170 is lowered out of the way of the screw-threaded member 166' of the shifter arm 141. When the shaft 55 is again placed in operation, the cam moves past the free end 35 of the lever 166 so that the spring will move this lever upwardly, thereby swinging the bell crank 170 to raise the end 171 and to raise the member 166 and the shifter arm 141 so that the carrier button engaged in 40 the end thereof will clear the centering pin 41 of the spindle 36. A lever 172 (see Figs. 19 and 23) is pivoted at 173 on the escapement housing 174 and has one end bent upwardly as at 175, on which is attached a 45 rest 176 having an intermediate lateral extension 177 (see Fig. 29) which rests on the upper end of the arm 168' of the lever 166. A bracket 179 is carried by the tone arm 22 for resting on the upper extremity of the 50 rest 176. When the free end of the lever 166 is in its raised position, the rest 176 holds the tone arm 22 with its sound box 23 raised above the turn table 24. An adjustable stop 180 is associated with the bracket 179 to limit the outward swinging 55 movement of the tone arm 22 so as to place the stylus of the sound box in engagement with the outer groove of the record when the rest is lowered by the engagement of the cam 165 with the free end of the lever 166, thereby allowing the lever 172 to swing downwardly with the rest 176. As the lever 172 moves downwardly, it actuates an escapement mechanism in the housing 174 so as 60 to prevent the stylus injuring the record as

it is let down into engagement therewith. The association between the lever 172 and the escapement mechanism is accomplished through the bracket 182 on the lever 172. On this bracket 182 there is mounted a 70 spring pressed pawl 183 engageable with a ratchet wheel 184 rotatable on a shaft 185 journaled in the housing 174. A second ratchet wheel 186 is also rotatable on the shaft 185, and is engageable by the spring 75 pressed pawls 187 pivoted on the wheel 184. A train of gears 188 are operatively associated with the wheel 184 for causing rotation of the wind brake 189. It will therefore be seen that as soon as the upper end 80 of the arm 168' is moved downwardly from the extension 177 of the rest 176, that the weight of the tone arm and the sound box will slowly move the lever 172 downwardly because of the engagement of pawl 183 with the wheel 184 of the escapement mechanism 85

An abutting arm 190 is hinged at one end to one side of the shifter arm 141 as is indicated at 191 and extends across the shifter arm. An adjustment screw 192 is engaged with the abutment arm 190 so that the height of the free end thereof may be varied for properly abutting one end of the bracket 179 so that as the shifter arm moves over to deposit a record on the turn table, the free end 90 of the abutment arm 190 will abut the adjacent end of the bracket 179 to engage the adjustable stop 180 with the rest 176, thereby placing the stylus of the sound box 95 23 in such a position that when the sound box 100 is lowered as heretofore indicated it will engage with the outermost portion of the record groove. As said sound box is being lowered, the bracket lowers to a position below the free end of the abutment arm, and consequently as the tone arm and sound box are moved inwardly by the record groove, said bracket passes under the abutment arm 190, and will raise the same to some extent. When, however, the shifter arm is 105 raised by the bell crank 170 as heretofore indicated, the abutment arm will be swung back into approximately its original position, and then as the shifter arm is moved to return the record to the magazine, the abutment arm will slip off of the bracket 179 to again be in the proper position for engaging the bracket to restore the tone arm 110 to the proper position for lowering the sound box to engage the stylus with the outer portion of the record groove. 115

A pin 193 extends laterally from the lift lever 94 and projects through the notch 194 at the free end of a crank 195 fixed on the shaft 185 of the escapement mechanism 120 so that as the lift lever moves downwardly, said crank 195 is moved downwardly, thereby rotating the ratchet wheel 186 so as to engage with the pawls 187 to rotate the wheel 184 (Fig. 23) and the gearing 188 and 125 130

the wind brake 189, thus easing the downward movement of the magazine preventing the same from falling and stopping in a jerky manner.

5 When the magazine is being lifted upwardly by the lift lever 94, the turn of the crank 195 will cause the rotation of the ratchet wheel 186 in the opposite direction so as to slip in relation to the pawls 187 and in 10 no way effect the escapement mechanism. I shall now proceed with a detailed description of the means for placing the main shaft 55 into and out of operation by a clutch mechanism which is associated therewith 15 and with a drive indirectly connected with the motor 28. A shaft 196 (see Fig. 11) is journaled in a bracket 197 mounted on the governor bracket 33 and in a bracket 198 on the bracket arm 48. The hub 38 of the 20 turn table 24 is provided with a beveled gear portion 199 meshing with a bevel pinion 200 fixed on one end of the shaft 196. A pin 201 projects radially from the shaft 196 (Figs. 9 and 10) for engaging a ratchet face 25 202 on one end of a pinion 203 which is slidable and rotatable on the shaft 196. This pinion 203 meshes with the gear 61 on the main shaft 55 for performing the operation heretofore explained. The gear 61 has 30 an opening 204 therein. A bracket arm 205 pivotally supports, as at 206, a bell crank 207 one end of which is provided with a fork extension 208 straddling the ratchet faced portion 202 of the pinion 203. A dog 209 35 is pivoted on the end of the bell crank 207 having the fork extension 208, and is engageable with the opening 204 of the gear 61. A bell crank 210 is pivoted at 211 (Fig. 5) to the bracket 212. One arm of the bell 40 crank 210 has a hook 213 as has also the other end of the other bell crank 207 as is indicated at 214. An expandable coil spring 215 is engaged between these hooks 213 and 214 for normally holding the bell crank 207 so that the forked extension 208 will maintain the ratchet portion 202 of the pinion 203 45 in an engageable position with the pin 201 projecting from the shaft 196.

A link 216 is disposed between the end 50 of the bell crank 210 having the hook 213 and the dog 209 so that the spring 215 will also maintain the dog 209 in engagement with the gear 61 so as to be engaged by the opening 204, through the intermediacy of the 55 link 216 and the hook end 213. A rod 218 is pivotally engaged with the other end of the bell crank 210 as at 219 so that by pulling upon this rod 218 the bell crank 210 may be swung to release the tension of the spring 215 and simultaneously pull the link 216 to 60 disengage the pawl 209. This swinging of the bell crank 210 tensions the springs 215 so that the bell crank 207 is swung to shift the pinion 203 and its ratchet portion 202

for engaging the pin 201. A bearing 65 bracket 220 is supported by the arm 221 projecting from the side rail of the frame 27 (Fig. 5) and rotatably supports a shaft 222 (Fig. 30) having a crank rod 223 projecting therefrom having a terminal extension 70 224 terminating above a gear wheel 225 which is rotatable on the frame portion extending rearwardly from the front rails of the frame 27.

The gear wheel 225 has peripheral bevel 75 gear teeth 226 meshing with the bevel gear segment 199 on the hub 38 of the turn table 24. A cam strip 227 starts adjacent the axis of the wheel 225 and is curved a portion of the convolution of a spiral as at 228 and 80 terminates in a substantially straight portion disposed tangentially of the axis of the wheel 225 for engaging the terminal 224 and swinging the rod 223 outwardly. A return cam strip 229 is adapted to be brought into 85 engagement with the terminal 224 as the wheel rotates, and after said terminal disengages from the cam 227 for returning it inwardly to a position on the dotted line circle 230 in Figure 9, so as to be engaged 90 by a cam strip 231 which is disposed substantially parallel with the straight portion of the cam strip 227 and spaced a distance outwardly therefrom. When the terminal 224 is engaged by the cam strip 231 it is delivered into engagement with the cam strip 229 to be returned to the position illustrated 95 in Figure 9. The rotary motion of the wheel 225, therefore, is transformed into the oscillatory movement of the rod 223. A crank 100 233 is formed integrally with the rod 223 and projects radially from the shaft 222 and has a pin 234 rising therefrom. A bracket 235 is rotatable with the tone arm 22 and has pivoted thereto as at 236 a bar 237 having a 105 slotted end 238 for receiving the pin 234. As is shown to advantage in Figure 34 the pivot pin 236 rises from the bracket 235 and has its upper end threaded for the reception of a tensioning nut 239. A friction washer 110 240 rests on the pivoted end of the bar 237 and is prevented from rotation by a stud 241 rising from the bracket 235 and piercing the washer 240. An expansion coil spring 242 is disposed about the pivot pin 236, being tensioned by nuts 239 to impinge against the washer 240 for holding it in frictional engagement with the pivoted end of the bar 237 so that said bar 237 will have a tendency 115 to swing with the bracket 235. It will thus be seen that as the stylus of the sound box 23 moves radially inwardly of the record, the bracket 235 tends to swing the bar 237, referring particularly to Figure 5, in a clockwise direction, thereby urging the rod 223 also in a clockwise direction so that the terminal 224 thereof will shift from the position 120 230 shown in Figure 9 to the position 125

shown in Figure 5 for being engaged by the cam strip 227. Thus, the rod 223 will be urged outwardly by the inner cam 227 as long as the sound box is moving inwardly and radially of the record. Whenever the sound box reaches the end of the record groove and thereby ceases its inward and radial movement, the terminal of the rod 223 will no longer be urged inwardly but will be left by the cam strip 229 in the position 230 as shown in Figure 9 for being actuated by the cam strip 231. The throw of the rod 223 by this cam strip 231 is greater than its throw by the cam strip 227 so that the intermediate portion of the rod 223 will engage the hook terminal of the hook rod 218 for swinging the bell cranks 210 and 207 as heretofore indicated for the purpose of engaging the clutch formed by ratchet segment 202 and pin 201 and simultaneously disengaging the dog 209 from the opening 204 in the gear 61.

As is well known, a certain make of disc records have their sound groove terminating in a sinuous spiral, which would cause the sound box and tone arm to oscillate when the stylus of the sound arm was engaged therewith. To compensate for this oscillatory movement of the tone arm which would tend to oscillate the bracket 235, the bar 237 and the rod 223 I provide a spring finger 244 which will engage the bearing bracket 220 when the rod 223 is swung inwardly and force the same outwardly so that the free end thereof will engage the cam strip 231 rather than the cam strip 227, thus causing the desired pull on the hook rod 218.

A bracket 245 (see Fig. 5) is fixed to the frame and extends over a portion of the wheel 225. A recess 246 is provided in the bottom edge of the bracket 245 and limits the movement of the rod 223 as is clearly shown in Figures 6 and 7. A catch 247 is pivoted at 248 to the bracket 245 and is provided with a notch 249 which engages the rod 223 as it is urged inwardly by the movement of the tone arm through the bracket 235, bar 237, pin 234, and crank 233. The nose of the catch 247 is beveled as indicated at 250 so that as the rod 223 is being swung through the movement of the tone arm inwardly of the record it will first engage the beveled portion 250 to raise the catch until the rod reaches the notch 249 at which time the catch will gravitate downwardly and thus hold the rod 223 against vibration and wobbling in a position so that its terminal 224 will be situated to be engaged by the inner cam strip 227. A foot 251 is projected from an intermediate portion of the catch 247 through a slot 252 and will be engaged by a humped plate 253 mounted on the wheel 225 just as the terminal 224 is about to be engaged by the cam 227. The slot 252

limits the swinging movement of the catch 247 as will be apparent.

An arm 254 is pivoted on the bracket 255 as at 256, and extends transversely of the hook rod 218. This rod 218 pierces the arm 254. The free end of the arm 254 terminates above the extension 177 of the rest 176 so that as said rest is moved upwardly, said arm 254 is swung upwardly for raising the rod 218 out of an engaging position with rod 223. A catch 258 is constructed with a shoulder 259 and at its free end has an offset extension 260. At the pivoted end of the catch 258 there is extended laterally an arm 261 having on its terminal a weight 262 which normally holds the catch in a raised position so that the shoulder 259 is engaged with or engageable with an arm 263 on the free end of the arm 254, as is best shown in Figure 18. As is shown to advantage in Figure 23, the catch 258 is pivoted on a depending bracket 264 on the bracket arm 49. The bracket 179 has a depending pin 266 which will engage the offset end 260 of the catch 258 to release the shoulder 259 from the arm 263 as the tone arm is moved toward the center of the record. The abutment between the pin 266 and the offset extension 260 will take place when the sound box has approached the end of the record. When the sound box approaches the end of the record, the arm 254 moves downwardly, thereby bringing the rod 218 into an engageable position by the rod 223 when it is swung by the cam strip 231. A guide yoke 270 rises from the bracket arm 48 for limiting and guiding the swinging movement of the arm 254. The bottom end of the shaft 132 has a cylindrical member 271 mounted thereon of insulating material held in place by a removable collar 272. An arcuate band 273 extends around approximately half of the cylindrical insulating member 271. The band 273 is of electricity conducting material. A pair of switch fingers 274 are in engagement with either the member 271 or the member 273, as is clearly shown in Figure 33, taken with Figure 24. It will thus be seen that the switch is closed when the two fingers 274 are engaged with the band 273. The band 273 is so located on the member 271 that the contact fingers 274 will be engaged therewith as soon as the shifter arm engages a record and during its movement with the record to the turn table and back again and the band will be disengaged from the fingers after the record has been deposited in its proper place in the magazine.

A damper 275 (Fig. 29) is mounted in the socket 21 and is operable by the shaft 276 on which is disposed a weighted crank 277 (Fig. 5) for holding the damper plate either open or closed. The outer end of the shaft

276 is enlarged to provide a key opening 278 into which may be inserted the key 279 (Fig. 35) so that the damper may be swung to either a closed or opened position, as desired.

A coin entrance slot-way 280 extends through the front wall of the cabinet and inclines downwardly and inwardly. An auxiliary slot way 281 is pivoted intermediate its ends to the inner end of the slot way 280 and is balanced so as to be normally in alignment with the slot way 280. A receptacle 282 is disposed at the inner extremity of the auxiliary slot way 281 so that if a coin of lighter weight than the proper coin is placed in the slot way 280 it will pass through the auxiliary slot way 281 and drop into the receptacle 282. However, if the coin placed in the slot way 280 is of the proper weight it will tilt the slot way 281 as soon as it engages therewith to be delivered to the slot way 283 which leads to the coin controlled circuit closing mechanism 284 of conventional construction which includes among other elements a releasing bellows 285 (Fig. 12) which in this instance is controlled by a link 286 engaged therewith and also engaged with a bell crank 287 having a spring 289 on the other end thereof. A link 290 connects the spring 289 with a crank 291 on a shaft 292 having a crank 293 (Fig. 19) at the other end thereof actuatable by the cam 165 so that as soon as a record has started to be moved from the magazine by the shifter arm, the main shaft 55 will have rotated sufficiently to cause the cam 165 to start swinging the crank 293 for the purpose of compressing the bellows 285 through the link 286, bell crank 287, spring 289, link 290, and crank 291. As the coin control switch 284 is otherwise of conventional construction, no further detailed description thereof is thought necessary or desirable in this application.

Attention is now directed to the wiring diagram shown in Figure 36 wherein it will be seen that the leads 295 and 296 are adapted to be connected with any suitable source of electrical energy in any well known manner. One lead is connected directly with the motor 28. This lead 295 has a branch 297 leading to the electric bulb 14. The other lead 296 terminates at one terminal 298 of a manual switch 299. One portion 300 of the coin controlled switch mechanism 284 is engaged with an intermediate portion of the lead 297. A wire 302 leads from the other terminal of the manual switch 299 to one of the fingers 274. The other switch member 303 of the coin controlled switch mechanism 284 is engaged with an intermediate portion of the wire 202. The other finger 274 is connected with the lead 296. A wire 304 leads from the finger 274 connected to wires 302 to the other terminal of the motor 28.

and has a branch 305 extending from the wire 304 to the other terminal of the electric bulb 14. It will be seen that if either the manual switch 299 or the coin controlled switch mechanism 284 is closed, that the current will flow through the lead 296, through either switch, through wire 302, through wire 304 to the motor and through branch 305 to the bulb 14 and return through branch 297 and lead 295. If the manual switch 299 is closed, the apparatus will run continuously. However, if the coin controlled switch mechanism is closed, it will be immediately opened as soon as the shifter arm has engaged with a record as previously explained, but at this time the switch on the shaft 132 will have closed since the band 273 will have been brought in engagement with both fingers 274 so that the current will flow through the lead 296 through the fingers 274 and band 273 and through the wire 304 as previously explained.

It is thought that the details of construction have now been explained sufficiently to follow the complete operation of the machine. Assuming that the parts are in their normal idle position as is indicated in Figure 2 it will be seen that as soon as a coin of the proper size has been dropped into the chute 280 the motor circuit will be closed so that the energization of this motor will start the rotation of the spindle 36 through the intermediacy of the governor mechanism previously described in detail. The rotation of the spindle 36 causes simultaneous rotation of a shaft 196 through the rotation of the turn table 24 and its gear 199, and at the same time imparts rotary motion to the wheel 225. At the start of the motor, the rotation of the shaft 196 will be imparted to the pinion 203 since the clutch previously referred to in detail is closed as is indicated in Figure 9, but the dog 209 is out of engagement with the opening 204 so that rotary motion is imparted to the gear 61 and the main shaft 55. The initial rotation of the shaft 55 will immediately start the rotation of the hub 67 as previously explained, thereby swinging the crank 88 so that its roller 89 will engage the star wheel 92 for shifting the record magazine either up or down, depending upon the position of the heart shaped cam 93. As soon as the roller 89 disengages from the star wheel 92, the shaft 55 has rotated sufficiently to cause the meshing of the inner arcuate series of teeth 131 with the gear segment 134 of the milled gear 133 on the shaft 132 for causing the shifter arm 141 to swing into engagement with the carrier button and place the same with its record on the turn table. As soon as the record is deposited on the turn table, the sound box and tone arm are lowered by the lowering of the rest 176 through

the operation of the cam 165 on the lever 166, as previously explained.

As the stylus approaches the end of the playing groove of the record, the pin 266 will trip the catch 258 and allow the arm 254 to drop. This places the hook rod 218 in an operative position in relation to the rod 223. The inward movement of the sound box causes the terminal of the rod 223 to be placed for engagement with the inner cam 227 so that the rod 223 will not pull upon the rod 218 until the sound box has come to the end of the record groove at which time the rod 223 will be swung by the cam 231 for pulling on the rod 218. At this time, attention is directed to the purpose of the opening 204 in the gear 61. As soon as the tone arm has been lowered to engage the stylus of the sound box in the entrance of the groove on the record, the gear 61 will have rotated sufficiently to bring the opening 204 for engagement with the dog 209, so that as this gear rotates a little further said dog 204 is pulled sufficiently to slide the pinion 203 so as to disengage its ratchet clutch face 202 from the pin 201 so that the gear 61 and the main shaft 55 cease to rotate.

As soon as the rod 218 is pulled, however, it swings the bell crank 210, thereby pulling on the link 216 to disengage the dog 209 from the opening 204 and simultaneously the swinging of the bell crank 210 causes the tensioning of spring 215 sufficiently to rock the bell crank 207 so as to cause the ratchet clutch segment 202 to be brought into engagement with the pin 201. The tension of the spring will be sufficient to maintain the bell crank 207 in this position and to also return the dog 209 to its engaging position with the gear 61 after the rod 223 is swung inwardly. Thus rotary motion is again imparted to the gear 61 and the main shaft 55 from the shaft 196. As the main shaft 55 starts its second rotation, the free end of the lever 166 slips off the end of the cam 165 and is raised by spring 167 so as to lift the rest 176 and swing the bell crank 170 to raise the shifter arm sufficiently to lift its foot 162 out of the recess 161 of the track 160. The continued rotation of the main shaft 55 now brings the outer series of teeth 130 into engagement with the gear segment 136 of the mutilated gear 135 so as to return the record to the magazine and to open the switch on the end of the shaft 132 for stopping the motor.

It is now apparent from the foregoing description that my improved automatic phonograph has many advantages. It is automatic in its operation, all that is necessary to start the same to play is to close the manual switch or actuate the coin control switch. The machine automatically accommodates itself for the playing of records

having length sound grooves without any manual operation on the part of the operator. It is fool-proof, and positive in operation, and the parts are so arranged and connected as to brace each other, reducing vibration, and adding to the quality of the playing of the record. New records will be easily substituted for those already in the magazine without the necessity of dismantling any part of the machine, since the magazine may be raised by the operation of the knob 57 and the records on the shelves easily removed and the buttons therein inserted in new records may be placed on the shelves.

While in the description of my invention, I have referred to certain details of mechanical construction and arrangement of parts as well as to certain electric circuits, I do not limit myself thereto except as may be pointed out in the appended claims.

Having thus described the invention, what I claim as new is:

1. In talking machines, the combination with the sound box and operating motor, of mechanism for shifting the records into and out of operative relation with said sound box and motor mechanism and for restoring said sound box to initial position, a shaft for operating said shift mechanism, means operatively connecting said shaft with said motor mechanism, a pin extending through the shaft, a gear slidable and rotatable on the shaft, a ratchet clutch segment formed on the gear engageable with the pin and provided with an annular groove, a pivotally mounted bell crank having one end forked to engage the groove, a toothed wheel operatively connected with the motor mechanism, a cam strip on the wheel extending from a point adjacent its axis outwardly and non-radially, a second cam strip on the wheel extending from a point farther from said axis in parallel spaced relation along side of the first strip and terminating closer to the periphery of the wheel than the first strip, a pivotally mounted rod having its free end engageable with the cam strips, means upon which the rod is pivotally mounted, a crank on the other end of the rod, a third cam strip on the wheel coiled about the outer ends of the first and second cam strips in spaced relation thereto and then extending inwardly of the wheel and angularly to the first and second strips, a bracket, a pivoted catch on the bracket, a foot member attached to the catch, extending through a slot in the bracket to have its movement limited by the slot and extending downwardly, a hump member on the wheel for engaging the foot to move the catch out of engagement with the rod before said rod engages with the cam strips, a frictional actuating means operable by the movement of the sound box by the record being

- played for engaging the crank to urge the rod into engagement with the catch and the free end of the arm in the paths of movement of the cam strips, a second pivotally mounted bell crank, a link connecting one end of the second bell crank with one end of the first bell crank, a spring connecting said end of the second bell crank with the other end of the first bell crank, a hook, and elements engaged with the other end of the second bell crank and engageable by an intermediate portion of said rod when said rod is actuated by the second cam strip for the purpose of disengaging the ratchet clutch segment from the pin.
- 5 3. In a talking machine, the combination with the sound box and operating motor, of mechanism for shifting the records into and out of operative relation with said sound box and motor mechanism and for restoring said sound box to initial position, a shaft 70 operatively connected with the motor mechanism for operating said shifter mechanism, a driving element slidable and rotatable on the shaft for connecting said shaft with said shifter mechanism, a pin projecting from the clutch shaft, a ratchet clutch member on the 75 driving element and provided with an annular groove, a pivotally mounted bell crank having one end forked to engage the groove, a wheel operatively connected with the motor mechanism, a cam strip on the wheel 80 extending nonradially from a point adjacent the axis of the wheel, a second cam strip on the wheel extending from a point farther from the axis of the wheel and the first cam strip and along side of and substantially 85 parallel to and spaced from the first strip and terminating closer to the periphery of the wheel and first strip, a rod pivotally mounted to have one end engageable with the cam strips, means upon which the rod is 90 pivotally mounted, a third cam strip on the wheel coiled about the outer ends of the first and second cam strips in spaced relation 95 thereto and then extending inwardly toward the axis of the wheel and angularly in relation to the first and second cam strips, friction means between the sound box and the rod so that the movement of the sound box by the record being played will tend to urge the rod into an engaging position with the 100 first cam, the third cam then engaging the rod to leave it in a position to be normally engaged by the second cam, a second bell crank lever pivoted on the frame, a link connecting one end of the second bell crank 105 with one end of the first bell crank, a spring connecting the said end of the second bell crank with the other end of the first bell crank, a hook element engaged with the other end of the second bell crank and having a 110 lateral extension on its free end and engageable with an intermediate portion of said rod when said rod is actuated by the second cam strip for the purpose of disengaging the ratchet catch segment from the pin, a bracket 115 crossing the rod transversely, a pivoted catch on the bracket, a foot member attached to the catch, extending through a slot in the bracket to have its movement limited by the ends of the slot, and extending downwardly, 120 and a hump member on the wheel for engaging the foot to move the catch out of engagement with the rod before the rod engages said cam strip.
- 10 4. In a talking machine, the combination 125 130

- with the sound box and operating motor, of mechanism for shifting the records into and out of operative relation with said sound box and motor mechanism and for restoring said sound box to initial position, a shaft operatively connected with the motor mechanism for operating said shifter mechanism, a driving element slidable and rotatable on the shaft for connecting said shaft with said shifter mechanism, a pin projecting from the clutch shaft, a ratchet clutch member on the driving element and provided with an annular groove, a pivotally mounted bell crank having one end forked to engage the groove, a wheel operatively connected with the motor mechanism, a cam strip on the wheel extending nonradially from a point adjacent the axis of the wheel, a second cam strip on the wheel extending from a point farther from the axis of the wheel and the first cam strip and along side of and substantially parallel to and spaced from the first strip and terminating closer to the periphery of the wheel and first strip, a rod pivotally mounted to have one end engageable with the cam strips, means upon which the rod is pivotally mounted, a third cam strip on the wheel coiled about the outer ends of the first and second cam strips in spaced relation thereto and then extending inwardly toward the axis of the wheel and angularly in relation to the first and second cam strips, friction means between the sound box and the rod so that the movement of the sound box by the record being played will tend to urge the rod into an engaging position with the first cam, the third cam then engaging the rod to leave it in a position to be normally engaged by the second cam, and a hook element operatively connected with the bell crank and engageable with an intermediate portion of said rod when said rod is actuated by the second cam strip for the purpose of disengaging the ratchet clutch segment from the pin.
5. In a talking machine, the combination with the sound box and operating motor, of mechanism for shifting the records into and out of operative relation with said sound box, and motor mechanism and for restoring said sound box to initial position, a shaft for operating said shifting mechanism, means operatively connecting said shaft with said motor mechanism, a clutch interposed between said last mentioned means and said motor mechanism, a frame, a bell crank pivotally mounted on the frame and having one end operatively connected with the clutch, a wheel operatively connected with the motor mechanism, a cam on said wheel, a second cam on said wheel adjacent the first cam and farther from the center of the wheel than the first cam, a rod pivotally mounted on the frame having its free end engageable with the cams to be urged outwardly there- by, a crank on the other end of the rod, a third cam on the wheel outside of the first and second cams and adapted to urge the free end of the rod inwardly to leave it for engagement by the second cam, a bracket, a pivoted catch on the bracket, a foot member attached to the catch, extending through a slot in the bracket to have its movement limited by the ends of said slot and extending downwardly, a hump member on the wheel for engaging the foot to move the catch out of engagement with the rod before said rod engages with the cams, a frictionally actuated means operable by the movement of the sound box by the record being played and engaged with the crank to urge the rod into engagement with the catch and the free end of the rod in the path of movement of the first cam, a second bell crank pivotally mounted on the frame, a link connecting one end of the second bell crank with a portion of the first bell crank adjacent said one end thereof, a spring connecting one end of the second bell crank with said other end of the first bell crank, a hook element engaged with the other end of the second bell crank and engageable by an intermediate portion of said rod to be pulled thereby when the rod is actuated by the second cam for the purpose of engaging the clutch.
6. In a talking machine, the combination with the sound box and operating motor, of mechanism for shifting the records into and out of operative relation with said sound box and motor mechanism and for restoring said sound box to initial position, a shaft operatively connected with the motor, a clutch for operatively connecting the shaft with said mechanism, a wheel operatively connected with the motor, a pivotally mounted rod, means upon which the rod is pivotally mounted, a frictional drive between the rod and the sound box for urging said rod inwardly of the wheel, as the sound box is moved by the record being played, a cam on said wheel with which said rod is engageable when urged inwardly, a second cam adjacent the first cam on the wheel and spaced a distance outwardly therefrom, and disposed to urge the rod outwardly when engaged therewith, a third cam on the wheel outside of the first and second cams adapted to engage the rod for urging it inwardly and leaving it for engagement by the second cam when said sound box has ceased its movement, and means operable by the rod when engaged by the second cam for throwing the clutch into an operative position.
7. In a talking machine, the combination with the sound box and operating motor, of mechanism for shifting the records into and out of operative relation with said sound box and motor and for restoring said sound box to initial position, a rotatable member operatively connected with the motor, a piv-

totally mounted rod having a free end terminating at the rotatable member, means upon which the member is rotatably mounted and the rod is pivotally mounted, a cam on the rotatable member engageable with the free end of the rod to urge it outwardly of the center of the rotatable member, a second cam on the rotatable member adjacent to and spaced outwardly from the first cam for urging the free end of the rod outwardly of the center of the rotatable member, a third cam on the rotatable member positioned to receive the free end of the rod after having been actuated by either the first or second cam to return it to a position for engagement by the second cam, means operable by the movement of the sound box for urging the rod to engage the first cam, and means for operatively engaging the mechanism with the motor, said means being actuated by the movement of said rod when engaged with the second cam.

8. In a talking machine, the combination with the sound box and operating motor, of mechanism for shifting the records into and out of operative relation with said sound box and motor and for restoring said sound box to initial position, a rotatable member operatively connected with the motor, a pivotally mounted rod having a free end terminating at the rotatable member, means upon which the member is rotatably mounted and the rod is pivotally mounted, a cam on the rotatable member engageable with the free end of the rod to urge it outwardly of the center of the rotatable member, a second cam on the rotatable member adjacent to and spaced outwardly from the first cam for urging the free end of the rod outwardly of the center of the rotatable member, a third cam on the rotatable member positioned to receive the free end of the rod after having been actuated by either the first or second cam to return it to a position for engagement by the second cam, means operable by the movement of the sound box for urging the rod to engage the first cam, and means for operatively engaging the mechanism with the motor, said means being actuated by the movement of said rod when engaged with the second cam.

9. In a talking machine, the combination with the sound box and operating motor, of mechanism for shifting the records into and out of operative relation with said sound box and motor and for restoring said sound box to initial position, a rotatable member operatively connected with the motor, a pivotally mounted rod having a free end terminating at the rotatable member, means upon which the member is rotatably mounted and the rod is pivotally mounted, a cam on the rotatable member engageable with the free end of the rod to urge it outwardly of the center of the rotatable member, a second cam on the rotatable member adjacent to and spaced outwardly from the first cam for urging the free end of the rod outwardly of the center of the rotatable member, a third cam on the rotatable member positioned to receive the free end of the rod after having been actuated by either the first or second cam to return it to a position for engagement by the second cam, means operable by the movement of the sound box for urging the rod to engage the first cam, and means for operatively engaging the mechanism with the motor, said means being actuated by the movement of said rod when engaged with the second cam.

10. In a talking machine, the combination with the sound box and operating motor, of mechanism for shifting the records into and out of operative relation with said sound box and motor and for restoring said sound box to initial position, a rotatable member operatively connected with the motor, a pivotally mounted rod having a free end terminating at the rotatable member, means upon which the member is rotatably mounted and the rod is pivotally mounted, a cam on the rotatable member engageable with the free end of the rod to urge it outwardly of the center of the rotatable member, a second cam on the rotatable member adjacent to and spaced outwardly from the first cam for urging the free end of the rod outwardly of the center of the rotatable member, a third cam on the rotatable member positioned to receive the free end of the rod after having been actuated by either the first or second cam to return it to a position for engagement by the second cam, means operable by the movement of the sound box for urging the rod to engage the first cam, and means for operatively engaging the mechanism with the motor, said means being actuated by the movement of said rod when engaged with the second cam.

11. In a talking machine, the combination with the sound box and operating motor, of mechanism for shifting the records into and out of operative relation with said sound box and motor and for restoring said sound box to initial position, an operating member for said mechanism, a frame, said member being rotatably mounted on the frame and having a recess therein, a clutch inter-

minating at the rotatable member, means upon which the member is rotatably mounted and the rod is pivotally mounted, a cam on the rotatable member engageable with the free end of the rod to urge it outwardly of the center of the rotatable member, a second cam on the rotatable member adjacent to and spaced outwardly from the first cam for urging the free end of the rod outwardly of the center of the rotatable member, a third cam on the rotatable member positioned to receive the free end of the rod after having been actuated by either the first or second cam to return it to a position for engagement by the second cam, means operable by the movement of the sound box for urging the rod to engage the first cam, and means for operatively engaging the mechanism with the motor, said means being actuated by the movement of said rod when engaged with the second cam, a bracket, a catch pivoted on said bracket and adapted to engage the rod when it is in position for engagement by the first cam, said bracket having a slot, a foot member projecting from the catch through the slot to be limited in its movement by the ends of said slot, and a hump element on the rotatable member for engaging the foot member to raise the catch out of engagement with the rod before it is engaged by the cam.

12. In a talking machine, the combination with the sound box and operating motor, of mechanism for shifting the record into and out of operative relation with said sound box and motor and for restoring said sound box to initial position, an operating member for said mechanism, said member being rotatably mounted and having a recess therein, a clutch interposed between the rotatable member and the motor, a pivoted member having a dog thereon engageable by the recess of the rotatable member, means upon which the member is rotatably mounted and the rod is pivotally mounted, said pivoted member being operatively connected with the clutch, means associated with the pivoted member for normally holding the clutch engaged, said rotatable member being adapted to rotate so that when its recess engages the dog, said pivoted member is swung to disengage the clutch, and means actuatable when the sound box reaches the end of the record being played for actuating the dog to release it from the recess so that the clutch will move into engagement.

13. In a talking machine, the combination with the sound box and operating motor, of mechanism for shifting the record into and out of operative relation with said sound box and motor and for restoring said sound box to initial position, an operating member for said mechanism, a frame, said member being rotatably mounted on the frame and having a recess therein, a clutch inter-

posed between the rotatable member and the motor, a member pivoted on the frame and having a dog thereon engageable by the recess of the rotatable member, said pivoted member being operatively connected with the clutch, means associated with the pivoted member for normally holding the clutch engaged, said rotatable member being adapted to rotate so that when its recess engages the dog, said pivoted member is swung to disengage the clutch, a rotatable element operatively connected with the motor, a rod pivoted on the frame, the free end of said pivoted rod terminating adjacent the rotatable element, a cam on the rotatable element disposed to engage the free end of the rod and urge it outwardly from the axis of said rotatable element, a second cam disposed adjacent the first cam and farther from the axis of the rotatable element than the first cam and disposed to urge the free end of the rod outwardly, and cam means on the rotatable element for engaging the free end of the arm after it has been moved outwardly by the first and second cam.

12. In a talking machine, the combination with the sound box and operating motor, of mechanism for shifting the record into and out of operative relation with said sound box and motor and for restoring said sound box to initial position, an operating member for said mechanism, a frame, said member being rotatably mounted on the frame and having a recess therein, a clutch interposed between the rotatable member and the motor, a member pivoted on the frame and having a dog thereon engageable by the recess of the rotatable member, said pivoted member being operatively connected with the clutch, means associated with the pivoted member for normally holding the clutch engaged, said rotatable member being adapted to rotate so that when its recess engages the dog, said pivoted member is swung to disengage the clutch, a rotatable element operatively connected with the motor, a rod pivoted on the frame, the free end of said pivoted rod terminating adjacent the rotatable element, a cam on the rotatable element disposed to engage the free end of the rod and urge it outwardly from the axis of said rotatable element, a second cam disposed adjacent the first cam and farther from the axis of the rotatable element than the first cam and disposed to urge the free end of the rod outwardly, and cam means on the rotatable element for engaging the free end of the arm after it has been moved outwardly by the first and second cam.

13. In a talking machine, the combination with the sound box and operating motor, of mechanism for shifting the record into and out of operative relation with said sound box and motor and for restoring said sound box to initial position, an operating member for said mechanism, a frame, said member being rotatably mounted on the frame and having a recess therein, a clutch interposed between the rotatable member and the motor, a member pivoted on the frame having a dog thereon engageable by the recess of the rotatable member, said pivoted member being operatively connected with the clutch, means associated with the pivoted member for normally holding the clutch engaged, said rotatable member being adapted to rotate so that when its recess engages the dog, said pivoted member is swung to disengage the clutch, a rotatable element operatively connected with the motor, a rod pivoted on the frame, the free end of said pivoted rod terminating adjacent the rotatable element, a cam on the rotatable element disposed to

return it into a position for engagement by the second cam, means controlled by the movement of the sound box by the record for urging said arm into a position for engagement by the first cam, and means operable by the rod for releasing the dog when said rod is moved by the second cam.

14. In a talking machine, the combination with the sound box and operating motor, of mechanism for shifting the record into and out of operative relation with said sound box and motor and for restoring said sound box to initial position, an operating member for said mechanism, a frame, said member being rotatably mounted on the frame and having a recess therein, a clutch interposed between the rotatable member and the motor, a member pivoted on the frame and having a dog thereon engageable by the recess of the rotatable member, said pivoted member being operatively connected with the clutch, means associated with the pivoted member for normally holding the clutch engaged, said rotatable member being adapted to rotate so that when its recess engages the dog, said pivoted member is swung to disengage the clutch, a rotatable element operatively connected with the motor, a rod pivoted on the frame, the free end of said pivoted rod terminating adjacent the rotatable element, a cam on the rotatable element disposed to engage the free end of the rod and urge it outwardly from the axis of said rotatable element, a second cam disposed adjacent the first cam and farther from the axis of the rotatable element than the first cam and disposed to urge the free end of the rod outwardly, and cam means on the rotatable element for engaging the free end of the arm after it has been moved outwardly by the first and second cam to return it into a position for engagement by the second cam, means for urging said arm into a position for engagement by the first cam, means for releasing the dog from the recess in the rotatable member, an actuating member for said last mentioned means engageable by said rod when actuated by the second cam, and means controlled by said mechanism for raising said actuating member out of engagement with said rod during the major portion of the movement of the sound box by the record and releasing it before the sound box reaches the end of the record.

15. An operating mechanism including, in combination, an oscillatory arm adapted to be swung a distance in one direction, a bar pivotally mounted on the arm, means for holding the bar in frictional engagement with the arm so that said bar has a tendency to swing with said arm, said bar having a slotted end, an oscillating rod, a crank on the rod projecting into the slot of the bar, a rotatable member mounted adjacent the

- free end of the rod, means for rotating the member, a cam on the rotatable member engageable with the free end of the rod to urge it outwardly of the axis of the rotatable member, a second cam on the rotatable member adjacent to and spaced outwardly from the first cam for engaging the free end of the rod and urging it outwardly of the axis of the rotatable member, a third cam on the rotatable member positioned to receive the free end of the rod after having been actuated by either the first or second cam to return said free end to a position for engagement by the second cam, the movement 15 of the arm urging the rod through the bar so that its free end will be in a position for engagement by the first cam, and an actuating member engageable with the rod to be pulled thereby.
- 20 15. An operating mechanism including, in combination, an oscillatory arm adapted to be swung a distance in one direction, a bar pivotally mounted on the arm, means for holding the bar in frictional engagement 25 with the arm so that said bar has a tendency to swing with said arm, said bar having a slotted end, an oscillating rod, a crank on the rod projecting into the slot of the bar, a rotatable member mounted adjacent the free 30 end of the rod, means for rotating the member, a cam on the rotatable member engageable with the free end of the rod to urge it outwardly of the axis of the rotatable member, a second cam on the rotatable member 35 adjacent to and spaced outwardly from the first cam for engaging the free end of the rod and urging it outwardly of the axis of the rotatable member, a third cam on the rotatable member positioned to receive the 40 free end of the rod after having been actuated by either the first or second cam to return said free end to a position for engagement by the second cam, the movement of the arm urging the rod through the bar so 45 that its free end will be in a position for engagement by the first cam, an actuating member engageable with the rod to be pulled thereby, a bracket, a catch pivoted on said bracket and adapted to engage the rod when 50 it is in position for engagement by the first cam, said bracket having a slot, a foot member projecting from the catch through the slot to be limited in its movement by the ends of said slot, and a hump element on the 55 rotatable member for engaging the foot to raise the catch out of engagement with the rod before it is engaged by either of the cams.
- 60 16. In a talking machine, the combination with the sound box and operating motor, of mechanism for shifting the records into and out of operative relation with said sound box and motor and for restoring said sound box to initial position, a shaft for operating said mechanism, means operatively connect-
- ing said shaft with said motor, a pinion 65 slideable and rotatable on the shaft, a ratchet clutch segment formed on the pinion and provided with an annular groove, a frame, a pivotally mounted bell crank on the frame 70 having one end forked to engage the groove, a gear wheel for operating the mechanism and with which the pinion is meshable and provided with a recess, a spring pressed dog pivoted on the forked end of the bell crank 75 to be engaged by the recess so that the continued rotation of the gear will pull the dog and swing the bell crank to slide the pinion out of mesh with the gear, a rotatable member on the frame being operatively connected with the motor, a pivotally mounted rod on the frame having a free end terminating adjacent the rotatable member, a cam on the rotatable member engageable with the free 80 end of the rod to urge it outwardly of the axis of the rotatable member, a second cam on the rotatable member adjacent to and spaced outwardly from the first cam for urging the free end of the rod outwardly of the axis of the rotatable member, a third 85 cam on the rotatable member positioned to receive the free end of the rod after having been actuated by either the first or second cams to return it to a position for engagement by the second cams, means operable 90 by the movement of the sound box for urging the rod to engage the first cam, a second pivotally mounted bell crank, a link connecting one end of the second bell crank with the dog, a spring connecting said end 95 of the second bell crank and the other end of the first bell crank, a hook element engaged with the other end of the second bell crank and engageable by an intermediate portion of said rod when said rod is actuated by the second cam for the purpose of 100 disengaging the dog from the recess and allowing the spring to swing the first bell crank so that the ratchet clutch segment engages a pin on said shaft so that the pinion 105 operates with said shaft and rotates said gear for placing said mechanism in operation.
17. In a talking machine, the combination with the sound box and operating motor, of 110 mechanism for shifting the records into and out of operative relation with said sound box and motor and for restoring said sound box to initial position, a shaft for operating said mechanism, means operatively connect- 115 ing said shaft with said motor, a pinion slideable and rotatable on the shaft, a ratchet clutch segment formed on the pinion and provided with an annular groove, a pivotally mounted bell crank having one end 120 forked to engage the groove, a gear wheel for operating the mechanism and with which the pinion is meshable and provided with a recess, a spring pressed dog pivoted on the forked end of the bell crank to be engaged 125
- 65 16. In a talking machine, the combination with the sound box and operating motor, of mechanism for shifting the records into and out of operative relation with said sound box and motor and for restoring said sound box to initial position, a shaft for operating said mechanism, means operatively connect-
- 130

by the recess so that the continued rotation of the gear will pull the dog to swing the bell crank to slide the pinion out of mesh with the gear, a rotatable member operatively connected with the motor, a pivotally mounted rod having a free end terminating adjacent the rotatable member, a cam on the rotatable member engageable with the free end of the rod to urge it outwardly of the axis of the rotatable member, a second cam on the rotatable member adjacent to and spaced outwardly from the first cam for urging the free end of the rod outwardly of the axis of the rotatable member, a third cam on the rotatable member positioned to receive the free end of the rod after having been actuated by either the first or second cams to return it to a position for engagement by the second cams, means operable by the movement of the sound box for urging the rod to engage the first cam, a second pivotally mounted bell crank, a link connecting one end of the second bell crank with the dog, a spring connecting said end of the second bell crank and the other end of the first bell crank, a hook element engaged with the other end of the second bell crank and engageable by an intermediate portion of said rod when said rod is actuated by the second cam for the purpose of disengaging the dog from the recess and allowing the spring to swing the first bell crank so that the ratchet clutch segment engages a pin on said shaft so that the pinion operates with said shaft and rotates said gear for placing said mechanism in operation, a bracket, a pivoted catch on the bracket engageable with the rod to hold it in a position for engagement by the first cam, a foot member on the catch, and a hump element on the rotatable member engageable with the foot element to raise the catch before the free end of the rod is engaged by either cam.

18. In a talking machine, the combination with the sound box and operating motor, of mechanism for shifting the records into and out of operative relation with said sound box and motor and for restoring said sound box to initial position, a shaft for operating said mechanism, means operatively connecting said shaft with said motor, a pinion slidable and rotatable on the shaft, a ratchet clutch segment formed on the pinion and provided with an annular groove, a pivotally mounted bell crank having one end forked to engage the groove, a gear wheel for operating the mechanism and with which the pinion is meshable and provided with a recess, a spring pressed dog pivoted on the forked end of the bell crank to be engaged by the recess so that the continued rotation of the gear will pull the dog to swing the bell crank to slide the pinion out of mesh with the gear, a rotatable member opera-

tively connected with the motor, a pivotally mounted rod having a free end terminating adjacent the rotatable member, a cam on the rotatable member engageable with the free end of the rod to urge it outwardly of the axis of the rotatable member, a second cam on the rotatable member adjacent to and spaced outwardly from the first cam for urging the free end of the rod outwardly of the axis of the rotatable member, a third cam on the rotatable member positioned to receive the free end of the rod after having been actuated by either the first or second cams to return it to a position for engagement by the second cams, means operable by the movement of the sound box for urging the rod to engage the first cam, a second pivotally mounted bell crank, a link connecting one end of the second bell crank with the dog, a spring connecting said end of the second bell crank and the other end of the first bell crank, a hook element engaged with the other end of the second bell crank and engageable by an intermediate portion of said rod when said rod is actuated by the second cam for the purpose of disengaging the dog from the recess and allowing the spring to swing the first bell crank so that the ratchet clutch segment engages a pin on said shaft so that the pinion operates with said shaft and rotates said gear for placing said mechanism in operation, a bracket, a pivoted catch on the bracket engageable with the rod to hold it in a position for engagement by the first cam, a foot member on the catch, and a hump element on the rotatable member engageable with the foot element to raise the catch before the free end of the rod is engaged by either cam, means controllable and operable by the mechanism for raising said hook element out of engagement with the rod during the playing of the major portion of a record, and a releasing device operable by the movement of the sound box at the end of the record to release said last mentioned means so that the hook element engages said rod to be actuated thereby when said rod is swung by the second cam.

19. A talking machine having means for changing rotary motion into oscillatory motion including a driven oscillating rod, a rotary drive member, a cam on the rotary member with which the free end of the rod is engageable, said cam being disposed to move the free end outwardly from the axis of the rotatable member, and a second cam on the rotary member with which the free end of the rod is engageable after it leaves the first cam, said second cam being disposed to move the free end inwardly toward the axis of the rotatable member.

20. A talking machine having means for changing rotary motion into oscillatory motion including a driven oscillatory rod, a rotary drive member, a cam on the rotary

- member with which the free end of the rod is engageable, said cam being disposed to move the free end outwardly from the axis of the rotatable member, a second cam on the rotary member with which the free end of the rod is engageable, said second cam being disposed adjacent the first cam and positioned to move the free end of the rod outwardly from the axis of the rotary member, 5 the inner end of the second cam being disposed farther from the axis of the rotary member than the inner end of the first cam, a third cam on the rotary member with which the free end of the rod is engageable 10 after it leaves either the first or second cam, said second cam being disposed to move the free end inwardly toward the axis of the rotatable member to leave it in a position to be engaged by the second cam, an oscillatory arm adapted to be moved slowly in one direction, friction means disposed between the arm and the rod for urging the rod, as the arm moves, to engage with the first cam 15 after leaving the third cam so that when said arm ceases to move, the free end of the rod leaving the third cam will engage the second cam whereby the arc of movement of the rod is changed. 20
21. In a talking machine, the combination with the sound box and operating motor, of mechanism for shifting the rod into and out of operative relation with said sound box and motor and for restoring said sound box to initial position, clutch means for operatively connecting said mechanism with said motor, an oscillating rod, a member for operating the clutch means having an engagement with the intermediate portion of said rod when it oscillates in a predetermined 25 arc for the purpose of engaging the clutch means to start the mechanism, a rotatable member operatively connected with the motor, means for changing the rotary motion of the rotary member into oscillatory motion 30 of the rod so that said rod may oscillate in two different arcs, and means whereby the movement of the sound box by the record allows oscillatory motion to be imparted to the rod which will not operate the operating 35 member of the clutch means. 40
22. In a talking machine, a frame, a record magazine including a plurality of spaced shelves, means mounting the magazine for vertical movement in the frame, a V-shaped lever having one arm pivoted to the frame, and the other arm provided with a lateral extension, a grooved wheel journaled on the end of the lateral extension, a track member on the bottom of the magazine 45 engaged by said wheel, and detachable springs engaged with the first arm of the lever and with the frame tensioned to urge said magazine upwardly. 50
23. In a talking machine, a frame, a record magazine including a plurality of spaced shelves, means mounting the magazine for vertical movement in the frame, a V-shaped lever having one arm pivoted to the frame, and the other arm provided with a lateral extension, a grooved wheel journaled on the end of the lateral extension, a track member on the bottom of the magazine 55 engaged by said wheel, detachable 60
- spaced shelves, means mounting the magazine for vertical movement in the frame, a V-shaped lever having one arm pivoted to the frame, and the other arm provided with a lateral extension, a grooved wheel journaled on the end of the lateral extension, a track member on the bottom of the magazine engaged by said wheel, detachable 65

springs engaged with the first arm of the lever and with the frame and tensioned to urge said magazine upwardly, a counter shaft journaled in the frame, a heart shaped cam member fixed on the counter shaft and having a plurality of spaces, one corresponding to each shelf, a star wheel fixed on the counter shaft, a main shaft journaled in the frame, a manually actuated shaft journaled in the frame in extension of and in alignment with the main shaft, a crank having a collar on one end, said collar being rotatable on the manually actuated shaft, said collar having a pair of ratchet clutch segments formed on the opposite sides thereof, a sleeve having a ratchet clutch face engageable with one clutch segment of the collar, said sleeve being splined on the manually actuated shaft and formed with an annular groove, a second lever pivoted at one end to the frame and having a curved portion intermediate its ends and its free end extended laterally, a projection on the second lever and terminating in the groove of the sleeve at the curved portion of said lever, a spring attached to the free end of the lever and the frame for normally urging the ratchet clutch face of the sleeve in engaging position in relation to one of the ratchet clutch segments of the collar, a disc segment fixed to the counter shaft having one end beveled to engage the free end of the second lever to move it so as to tension the spring and disengage said ratchet clutch face, said disc segment maintaining the ratchet clutch face in its disengaged position until the free end of the second lever slips off the other end of the disc segment, said disc segment having a ratchet clutch face engageable by the other ratchet clutch segment, said sleeve having a counter bore, a spring disposed about the manually operated shaft having one end in the counter bore, and the other end impinged against the collar of the second lever for holding said other ratchet segment in engaging position with relation to the ratchet clutch face on the disc segment, a sound box, an operating motor, and mechanism for shifting the records into and out of operative relation with said sound box and the shelves of said magazine and for restoring said sound box to initial position, said mechanism including said main shaft so as to rotate the disc segment to disengage the clutch face of the sleeve and hold it disengaged while the clutch face of the disc segment rotates the crank for engaging it with the star wheel for shifting the magazine so that said mechanism will be operable with respect to another record in the magazine.

25. In a talking machine, a frame, a record magazine including a plurality of spaced shelves, means mounting the magazine for vertical movement in the frame, a

counter balance structure associated with said magazine, a lever pivoted at one end on the frame and having the other end slidably engaged with the bottom of the magazine, a counter shaft journaled in the frame, a heart shaped cam member fixed on the counter shaft and engageable with an intermediate portion of the lever, one corresponding to each shelf, means for rotating the shaft, and means for moving records out of the magazine and returning them to the magazine. 75

26. In a talking machine, a frame, a record magazine including a plurality of spaced shelves, means mounting the magazine for vertical movement in the frame, a counter balance structure associated with the magazine, a lever pivoted at one end to the frame and having its free end slidably engaged with the magazine, a heart cam mounted for rotation in the frame and engageable with an intermediate portion of the lever for raising and lowering the lever for placing the magazine in a desired position. 80

27. In a talking machine, a frame, a record magazine including a plurality of spaced shelves, means mounting the magazine for vertical movement in the frame, a counter balance structure associated with the magazine, a lever pivoted at one end to the frame and having its free end slidably engaged with the magazine, a heart cam mounted for rotation in the frame and engageable with an intermediate portion of the lever for raising and lowering the lever for placing the magazine in a desired position, a star wheel operatively associated with the heart cam, a main shaft journaled in the frame, a manually operated shaft journaled in the frame in alignment with the main shaft, a crank rotatable and slideable on the manually operated shaft and having its end engageable with the star wheel, clutch segments on the opposite sides of said crank, a spring pressed clutch segment splined to the manually operating shaft for association with one of the clutch segments of the crank, another clutch segment fixed to the main shaft for engaging the other clutch segment of the crank. 95 100 105 110 115

28. In a talking machine, a frame, a record magazine including a plurality of spaced shelves, means mounting the magazine for vertical movement in the frame, a counter balance structure associated with the magazine, a lever pivoted at one end to the frame and having its free end slidably engaged with the magazine, a heart cam mounted for rotation in the frame and engageable with an intermediate portion of the lever for raising and lowering the lever for placing the magazine in a desired position, a star wheel operatively associated with the heart cam, a main shaft journaled in the frame, a manually operated shaft 120 125 130

- journaled in the frame in alignment with the main shaft, a crank rotatable and slideable on the manually operated shaft and having its end engageable with the star 5 wheel, clutch segments on the opposite sides of said crank, a spring pressed clutch segment splined to the manually operating shaft for association with one of the clutch segments of the crank, another clutch segment 10 fixed to the main shaft for engaging the other clutch segment of the crank, and means on the main shaft for holding the clutch segment of the manually operating shaft in a non-engaging position when the 15 clutch segment of the main shaft is in an engaging position.
29. In a talking machine, a frame, a record magazine including a plurality of spaced shelves, means mounting the magazine 20 for vertical movement in the frame, a counter balance structure associated with the magazine, a lever pivoted at one end to the frame and having its free end slidably engaged with the magazine, a heart cam 25 mounted for rotation in the frame and engageable with an intermediate portion of the lever for raising and lowering the lever for placing the magazine in a desired position, a star wheel operatively associated with 30 the heart cam, a main shaft journaled in the frame, a manually operated shaft journaled in the frame in alignment with the main shaft, a crank rotatable and slideable on the manually operated shaft and having 35 its end engageable with the star wheel, clutch segments on the opposite sides of said crank, a spring pressed clutch segment splined to the manually operating shaft for association with one of the clutch segments 40 of the crank, another clutch segment fixed to the main shaft for engaging the other clutch segment of the crank, means on the main shaft for holding the clutch segment of the manually operating shaft in a non- 45 engaging position when the clutch segment of the main shaft is in an engaging position, a sound box, an operating motor, and mechanism operatively associated with the motor for shifting the records into and out 50 of operative relation with said sound box and motor mechanism from the magazine and for restoring the records to said magazine after being played, said mechanism including said main shaft so as to shift the 55 magazine so that said mechanism will be operative on different records.
30. In a talking machine, the combination with a horizontal turn table, an operating motor therefor, and a cooperating traveling 60 sound box, of a magazine for a number of disc records vertically movable to bring the records thereon adjacent said turn table, shifter mechanisms for moving the records from said magazine and for returning the 65 same thereto, a shaft, clutch means for op- eratively connecting the shaft with the motor, said shaft being operatively connected with said shifter mechanism, and means for holding said clutch in a disengaged position by the movement of the sound box on the 70 record being played, so that when said movement ceases, the clutch engages automatically for returning the record to the magazine through the shaft and the shifter mechanism. 75
31. In a talking machine, the combination with a sound box and operating motor, of mechanism operatively associated with the motor for shifting the records into and out of operative relation with said sound box 80 and motor, said mechanism comprising a frame, a main shaft journaled in the frame to be disposed horizontally, a gear on one end of the main shaft and rotatable therewith, a quadrant of beveled gear teeth on the periphery of the gear, a second quadrant of beveled gear teeth on the gear between the axis and periphery thereof, a vertical shaft journaled in the frame, a pair of beveled pinions on the vertical shaft, one of 85 said pinions being disposed above the axis of the horizontal shaft and the other below the axis of the horizontal shaft, the upper pinion being meshable with the inner quadrant of gear teeth, the lower pinion being 90 meshable with the outer quadrant of gear teeth, whereby the rotation of the horizontal shaft imparts oscillatory motion to the vertical shaft, and a shifter arm mounted on the upper end of the vertical shaft. 95
32. In a talking machine, the combination with a sound box and operating motor, of mechanism operatively associated with the motor for shifting the records into and out of operative relation with said sound box 100 and motor, said mechanism comprising a frame, a main shaft journaled in the frame to be disposed horizontally, a gear on one end of the main shaft and rotatable therewith, a quadrant of beveled gear teeth on the periphery of the gear, a second quadrant of beveled gear teeth on the gear between the axis and periphery thereof, a vertical shaft journaled in the frame, a pair of beveled pinions on the vertical shaft, one of 105 said pinions being disposed above the axis of the horizontal shaft and the other below the axis of the horizontal shaft, the upper pinion being meshable with the inner quadrant of gear teeth, the lower pinion being meshable with the outer quadrant of gear teeth, whereby the rotation of the horizontal shaft imparts oscillatory motion to the vertical shaft, and a shifter arm mounted on the upper end of the vertical shaft. 110
33. In a talking machine, the combination with a sound box and operating motor, of mechanism operatively associated with the motor for shifting the records into and out of operative relation with said sound box 115 and motor, said mechanism comprising a frame, a main shaft journaled in the frame to be disposed horizontally, a gear on one end of the main shaft and rotatable therewith, a quadrant of beveled gear teeth on the periphery of the gear, a second quadrant of beveled gear teeth on the gear between the axis and periphery thereof, a vertical shaft journaled in the frame, a pair of beveled pinions on the vertical shaft, one of 120 said pinions being disposed above the axis of the horizontal shaft and the other below the axis of the horizontal shaft, the upper pinion being meshable with the inner quadrant of gear teeth, the lower pinion being meshable with the outer quadrant of gear teeth, whereby the rotation of the horizontal shaft imparts oscillatory motion to the vertical shaft, and a shifter arm mounted on the upper end of the vertical shaft, said shifter arm being hingedly engaged with the vertical shaft, and means for swinging the shifter arm upwardly as it moves toward and away from an operative position in relation to the sound box and operating motor. 125
- 130

33. In a talking machine, the combination with the sound box, operating motor, and turn table, of mechanism for shifting the records into and out of operative relation with said sound box and turn table, said mechanism comprising a main shaft journaled in the frame of the talking machine, a gear on said shaft and rotatable therewith, a quadrant of beveled gear teeth on the periphery of the gear, a second quadrant of beveled gear teeth on the gear between the axis and periphery thereof, a vertical shaft journaled in the frame, a pair of beveled pinions on the vertical shaft meshable with the respective quadrants of beveled gear teeth on the gear so that the rotary motion of the main shaft imparts an oscillating motion to the vertical shaft, a record shifter arm hinged to the upper end of the vertical shaft, and means for raising the shifting arm to lift the records onto and from the turn table.
34. In a talking machine, the combination with the sound box, turn table, and operating motor therefor, of means for shifting the records into and out of operative relation with said sound box and turn table, said mechanism comprising a frame, a vertically adjustable record magazine, said mechanism including means for raising and lowering the magazine to place a record therein on substantially the same level with the turn table, a shaft journaled in the frame, a gear on the shaft and rotatable therewith, a quadrant of beveled gear teeth on the periphery of the gear, a second quadrant of beveled gear teeth on the gear between the axis and periphery thereof, said quadrants of beveled gear teeth being circumferentially spaced in respect to each other, a vertical shaft journaled in the frame, a pair of bevel pinions on the vertical shaft, one below and one above the axis of the main shaft, said pinions being meshable with the respective quadrants of beveled gear teeth so that the rotary motion of the main shaft imparts an oscillatory motion to the vertical shaft, means operatively connecting the main shaft with the motor, an arm on the vertical shaft for engaging a record from the magazine and carrying it over to the turn table, means for hinging the shifter arm on the vertical shaft, and means for raising and lowering the arm so as to lift from and place on the turn table the record carried by the arm.
35. In a talking machine, the combination with the sound box, turn table, and operating motor therefor, of means for shifting the records into and out of operative relation with said sound box and turn table, said mechanism comprising a frame, a vertically adjustable record magazine, said mechanism including means for raising and lowering the magazine to place a record therein on substantially the same level with the turn table, a shaft journaled in the frame, a gear on the shaft and rotatable therewith, a quadrant of beveled gear teeth on the periphery of the gear, a second quadrant of beveled gear teeth on the gear between the axis and periphery thereof, said quadrants of beveled gear teeth being circumferentially spaced in respect to each other, a vertical shaft journaled in the frame, a pair of bevel pinions on the vertical shaft, one below and one above the axis of the main shaft, said pinions being meshable with the respective quadrants of beveled gear teeth so that the rotary motion of the main shaft imparts an oscillatory motion to the vertical shaft, means operatively connecting the main shaft with the motor, and an arm on the vertical shaft for engaging a record from the magazine and carrying it over to the turn table.
36. In a talking machine, the combination with the sound box, turn table, and operating motor therefor, of mechanism for shifting the records into and out of operative relation with said sound box and said turn table, said mechanism comprising a vertical shaft, means for imparting oscillatory movement to said shaft from said motor, a shifter arm hingedly engaged with said shaft to be swung to and fro in relation to the turn table for the purpose of depositing a record thereon and removing said record therefrom, a track of arcuate formation disposed concentrically about the axis of said shaft, the portion of said track adjacent the turn table being inclined upwardly and there being a recess in the upper portion of the track, an adjustable foot on the shifter arm slideable on said track so that said arm is raised as the foot passes over the inclined portion and is then deposited in the recess so that the arm is lowered on the record.
37. In a talking machine, the combination with the sound box, turn table, and operating motor therefor, of mechanism for shifting the records into and out of operative relation with said sound box and said turn table, said mechanism comprising a vertical shaft, means for imparting oscillatory movement to said shaft from said motor, a shifter arm hingedly engaged with said shaft to be swung to and fro in relation to the turn table for the purpose of depositing a record thereon and removing said record therefrom, a track of arcuate formation disposed concentrically about the axis of said shaft, the portion of said track adjacent the turn table being inclined upwardly and there being provided a recess in the upper portion of the track, an adjustable foot on the shifter arm slideable on said track so that said arm is raised as the foot passes over the inclined portion and is then deposited in the recess so that the arm is lowered on the record, and means for raising the shifter arm

to raise the record from the turn table and raise the foot out of the recess just before said shifter arm returns to swing the record from the turn table.

38. In a talking machine, the combination with the sound box, turn table having a centering pin and operating motor therefor, of mechanism for shifting the records into and out of operative relation with said sound box and said turn table comprising an oscillating shaft, means operatively connecting the oscillating shaft to the motor, a shifter arm hinged to the oscillating shaft so that a record may be swung over and away from the turn table as the shaft oscillates, a foot projecting from the shifter arm, a rail on which the foot bears, said rail having an inclined intermediate portion so that the arm will be raised as it is swung over the turn table, thereby allowing the record carried thereby to clear the centering pin, said rail being provided with a recess into which the foot may drop to allow the record to be lowered onto the turn table, and means for raising the foot out of the recess and hold it raised as the arm is being swung to move the record off the turn table.
39. In a talking machine, the combination with the sound box, turn table having a centering pin and operating motor therefor, of mechanism for shifting the records into and out of operative relation with said sound box and turn table and for restoring said sound box to initial playing position and raising it to an inactive position of the record, said mechanism comprising a main shaft operatively associated with the motor, a second shaft, means for transposing the rotary motion of the main shaft to oscillatory motion of the second shaft, a shifter arm hingedly engaged on the second shaft to be swung thereby over and away from the turn table, an arcuate track disposed concentrically about the axis of the second shaft and having an inclined intermediate portion and a recess at the end adjacent to the turn table, a foot depending from an intermediate portion of the shifter arm for sliding on the track so that as said shifter arm is moved toward the turn table it is raised, a pivoted member for receiving the shifter arm when it has moved to place the center of a record over the center of the turn table, a second pivoted member associated with the first pivoted member for lowering and raising the same, means associated with the second pivoted member for raising and lowering the sound box in relation to the record, and means operable by the main shaft for moving the second pivoted member.
40. In a talking machine, the combination with a sound box, and operating motor, of mechanism for shifting the records into and out of operative relation with said sound box and motor mechanism including a shift-

er arm having an L-shaped notch adjacent its free end, a clamping rod slidable longitudinally of the arm and having a lateral projection therein, a bracket, a pair of arcuate rails on the bracket disposed concentrically with relation to the axis of the shifter arm, spaced circumferentially in relation to each other, one being closer to said axis than the other, the adjacent ends of said rails being offset laterally in opposite directions, said offset being engageable with one rail to disengage the gripping bar and engageable with the other rail to engage the gripping bar.

41. In a talking machine, the combination with a sound box, and operating motor therefor, of mechanism for shifting the records into and out of operative relation with said sound box and motor, and carrier buttons for the records, said mechanism including means for gripping said carrier buttons.

42. In a talking machine, the combination with a sound box, and operating motor therefor, of mechanism for shifting the records into and out of operative relation with said sound box and motor, carrier buttons for the records, said mechanism including means for gripping said carrier buttons, each record carrier button comprising a body projectible through the opening in a disc record, an annular flange disposed laterally of one end of the body, and a neck extending axially from the other end of the body and terminating in a head.

43. In a talking machine, the combination with the sound box of mechanism for restoring said sound box to playing position comprising a pivotally mounted lever, means for operating the lever for swinging the same downwardly, a spring normally holding the lever raised, an escapement mechanism, a second lever pivotally mounted in association with the escapement mechanism and having its free end resting on the first lever and a member associated with the second lever for raising and lowering the sound box, a shifter arm for moving records into and out of operative relation with said sound box and means on said shifter arm for moving the sound box to a position so that when it is lowered it engages the entrance groove of the record about to be played.

44. In a talking machine, a frame, a record magazine including a plurality of spaced shelves, means for movably mounting the magazine in the frame, a lever pivoted on the frame, means engaging the lever with the magazine, a rotatable member having a plurality of cam portions engaging the lever, one corresponding to each shelf, means for rotatably mounting the member in the frame, and means for rotating the member to rock the lever and shift the position of the magazine.

45. In a talking machine, a frame, a record magazine including a plurality of spaced

- shelves, means for movably mounting the magazine in the frame, a lever pivoted on the frame, means engaging the lever with the magazine, a rotatable member having a plurality of cam portions engaging the lever, one corresponding to each shelf, means for rotatably mounting the lever in the frame, means for rotating the member to rock the lever and shift the position of the magazine, and means for moving records out of the magazine and returning them to the magazine.
46. In a talking machine, a frame, a record magazine including a plurality of spaced shelves, means mounting the magazine for vertical movement in the frame, a counterbalance structure associated with the magazine, a lever pivoted at one end to the frame, and having its free end slidably engaged with the magazine, a cam mounted for rotation in the frame and having a plurality of cam surfaces one for each shelf of the magazine, said cam being engageable with an intermediate portion of the lever for raising and lowering the lever for placing the magazine in different desired positions.
47. In a talking machine, a frame, a record magazine including a plurality of spaced shelves, means mounting the magazine for vertical movement in the frame, a counter balanced structure associated with the magazine, a lever pivoted at one end to the frame, and having its free end slidably engaged with the magazine, a cam mounted for rotation in the frame and provided with a plurality of cam surfaces, one corresponding to each shelf of the magazine, said cam being engageable with the intermediate portion of the lever for raising and lowering the lever for bracing the magazine in different desired positions, and means for moving records out of the magazine and returning them to the magazine.
48. In a talking machine, a frame, a record magazine, means mounting the magazine for vertical movement in the frame, a counterbalancing mechanism in the frame and including a wheel, and a track member fixed to the magazine and engaged by the wheel.
49. In a talking machine, a frame, a record magazine, means mounting the magazine for vertical movement in the frame, a lever pivoted in the frame, a wheel journaled on the lever, a track member fixed to the magazine, and engaged by the wheel, and means operable through the lever for counterbalancing the magazine.
50. In a talking machine, a frame, a record magazine, means mounting the magazine for vertical movement in the frame, a counterbalancing mechanism in the frame including a wheel, a track member fixed to the magazine and engaged by the wheel, and means for moving the records out of the magazine and returning them to the magazine.
51. In a talking machine, a frame, a record magazine, means mounting the magazine for vertical movement in the frame, a lever pivoted in the frame, a wheel journaled on the lever, a track member fixed to the magazine and engaged by the wheel, means operable through the lever for counterbalancing the magazine, and means in the frame for moving records out of the magazine and returning them to the magazine.
52. In a talking machine, a frame, a record magazine including a plurality of spaced shelves, means mounting the magazine in the frame for vertical movement, a lever pivoted on the frame, means engaging the lever with the magazine, a rotatable member having a plurality of cam portions engaging the lever, one corresponding to each shelf, means for rotatably mounting the member in the frame, means for rotating the member to rock the lever and shift the position of the magazine, a counter-balancing mechanism including a wheel, and a track member fixed to the magazine and engaged by the wheel.
53. In a talking machine, a frame, a record mechanism including a plurality of spaced shelves, means mounting the magazine in the frame for vertical movement, a lever pivoted on the frame, means engaging the lever with the magazine, a rotatable member having a plurality of cam portions engaging the lever, one corresponding to each shelf, means for rotatably mounting the member in the frame, means for rotating the member to rock the lever and shift the position of the magazine, a second lever pivoted in the frame, a wheel journaled on the second lever, a track member fixed to the magazine and engaged by the wheel, and means operable through the lever for counterbalancing the magazine.
54. In a talking machine, a frame, a record magazine including a plurality of spaced shelves, means mounting the magazine in the frame for vertical movement, a lever pivoted on the frame, means engaging the lever with the magazine, a rotatable member having a plurality of cam portions engaging the lever, one corresponding to each shelf, means for rotatably mounting the member in the frame, means for rotating the member to rock the lever and shift the position of the magazine, a counter balancing mechanism including a wheel, a track member fixed to the magazine and engaged by the wheel, and means for moving records out of the magazine and returning them to the magazine.
55. In a talking machine, a frame, a record magazine including a plurality of spaced shelves, means mounting the magazine in the frame for vertical movement, a counterbalancing mechanism including a wheel, a track member fixed to the magazine and engaged by the wheel, and means for moving records out of the magazine and returning them to the magazine.

zine in the frame for vertical movement, a lever pivoted on the frame, means engaging the lever with the magazine, a rotatable member having a plurality of cam portions engaging the lever, one corresponding to each shelf, means for rotatably mounting the member in the frame, means for rotating the member to rock the lever and shift the position of the magazine, a second lever pivoted in the frame, a wheel journaled on the second lever, a track member fixed to the magazine and engaged by the wheel, means operable through the second lever for counterbalancing the magazine, and means for moving the records out of the magazine and returning them to the magazine.

56. In a talking machine, a frame, a record magazine having a plurality of spaced shelves, means mounting the magazine for vertical movement, a lever pivoted on the frame, means engaging the lever with the magazine, means for moving the lever to shift the magazine, a second lever pivoted on the frame, means engaging the second lever with the magazine, and means operable through the second lever to counter balance the magazine.

57. In a talking machine, a frame, a record magazine having a plurality of spaced shelves, means mounting the magazine for vertical movement, a lever pivoted on the frame, means engaging the lever with the magazine, means for moving the lever to shift the magazine, a second lever pivoted on the frame, means engaging the second lever with the magazine, means operable through the second lever to counterbalance the magazine, and means for moving records out of the magazine and returning them to the magazine.

58. In a talking machine, the combination with a rotatable record support, and a reproducing mechanism of a magazine, means mounting the magazine for vertical movement, counterbalancing means associated with the magazine, said magazine having vertically spaced shelves to form supports for record carriers and records, oscillatory means adapted to be automatically operated to periodically swing a carrier and its record from one shelf of the magazine to the rotatable record support and return the same to the said one shelf of the magazine, means actuated by said reproducing mechanism whereby the oscillatory means operates to return the record to the magazine when the reproducing mechanism arrives adjacent the center of the record, means for shifting the magazine after a record has been returned to the magazine, and means for locking the oscillatory means to the carrier in its movement to and fro between the rotatable record support and the magazine.

59. In a talking machine, the combination with a rotatable record support, and a re-

producing mechanism of a magazine adapted to form a support for a series of record carriers and records, an oscillatory member adapted to be operated to swing a carrier and its record from the magazine to the rotatable record support and return the same to the magazine, a bar, means slidably mounting the bar on the member, said bar being notched, said member being notched, and the inner end of the notch of the member being offset, an arcuate bracket mounted concentrically in respect to the swinging movement of the oscillatory member, a pair of arcuate rails concentrically mounted on the bracket in spaced circumferential relation, the adjacent ends of the rails having oppositely directed extensions, and means on the bar for engaging the rails and their extensions for shifting the bar to register and unregister the entrances to the notches, 85

60. In a talking machine, the combination with a rotatable record support and a reproducing mechanism of a magazine adapted to form a support for a series of record carriers, and records, an oscillatory member adapted to be operated to swing a carrier and its record from the magazine to the rotatable record support and return the same to the magazine, locking means on the member to grip a carrier during swinging movement of the member, an arcuate bracket mounted concentrically in respect to the swinging movement of the oscillatory member, a pair of arcuate rails concentrically mounted on the bracket in spaced circumferential relation, the adjacent ends of the rails having oppositely directed extensions, and an operating member projecting from the locking means to engage the rails and their extensions to cause actuations of the locking means.

61. In a talking machine, a frame, a record magazine including a plurality of spaced shelves, means mounting the magazine for vertical movement in the frame, a lever pivotally mounted in the frame, one end of the lever being provided with a lateral extension, a grooved wheel journaled on the end of the lateral extension, a track member fixed to the magazine and engaged by the wheel, and detachable springs engaged with the lever and with the frame and tensioned to urge said magazine upwardly through the lever, the wheel and the track member.

62. In a talking machine, a frame, a record magazine including a plurality of spaced shelves, means mounting the magazine for vertical movement in the frame, a lever pivotally mounted in the frame, one end of the lever being provided with a lateral extension, a wheel journaled on the lateral extension, a track member fixed to the magazine and engaged by the wheel, springs engaged with the lever and the frame and tensioned to swing the lever to counter-bal-

ance the magazine, a counter shaft journaled in the frame, a cam member fixed on the counter shaft and having a plurality of cam spaces one corresponding to each shelf, a 5 star wheel fixed on the counter shaft and having a notch corresponding to each shelf, a main shaft journaled in the frame, a manually actuated shaft journaled in the frame as an extension of and in alignment 10 with the main shafts, a crank having a collar on one end, said collar being rotatable on the manually actuated shaft, said collar having a pair of ratchet clutch segments formed on opposite sides thereof, a sleeve having a 15 ratchet clutch face engageable with one clutch segment of the collar, said sleeve being rotatable with and slidable on the manually actuated shaft and formed with an annular groove, a second lever pivoted at 20 one end to the frame and having a curved portion intermediate its ends and its free end extended laterally, a projection on the second lever and terminating in the groove of the sleeve, at the curved portion of said 25 lever, a spring attached to the free end of the lever and the frame for normally urging the ratchet clutch face of the sleeve in engaging position in relation to one of the ratchet clutch segments of the collar, a disc 30 segment fixed to the counter shaft having one end beveled to engage the free end of the second lever to move it so as to tension the second mentioned spring and disengage said ratchet clutch face, said disc segment 35 maintaining the ratchet clutch face in its disengaged position until the free end of the second lever slips off the other end of the disc segment, said disc segment having a ratchet clutch face engageable by the other 40 ratchet clutch segment, said sleeve having a counterbore, and a spring disposed about the manually operated shafts, having one end in the counterbore and the other end impinged against the collar of the lever for holding 45 said ratchet segment in engaging position in relation to the ratchet clutch face on the disc segment.

63. In a talking machine, the combination with a rotatable record support and a traveling sound box, of a record magazine, means 50 mounting the magazine for vertical movement, means for moving said magazine to select a record, counterbalancing means associated with said magazine, an escapement mechanism, means operatively connecting the magazine upon its downward movement only with said escapement mechanism, shifter mechanism for automatically moving the selected records to and from 55 said magazine, and into and out of operative position upon said record support, shifter mechanism for automatically raising and lowering said sound box and moving the same to starting position, driving means for 60

anisms, means for initiating the operation of said driving means and means for automatically arresting the same.

64. In a talking machine, the combination with a rotatable record support, and a traveling sound box, of a record magazine, means mounting the magazine for vertical movement, a counter-balancing mechanism associated with the magazine, an escapement mechanism, means connecting the escapement mechanism with the magazine only upon the downward movement of said magazine, means for moving said magazine to select a record, shifter mechanism for automatically moving the selected record to and from said magazine and into and out of operative position upon said record support, shifter mechanism for automatically raising and lowering said sound box and moving the same to starting position, driving means for said record support, said shifter mechanisms, and said means for moving the magazine, means for initiating the operation of said driving means, and means for automatically arresting the same. 90

65. In a talking machine, the combination with a rotatable record support, and a traveling sound box, of a magazine, means mounting the magazine for vertical movement, means for moving said magazine to 95 select a record, a counterbalancing mechanism, a wheel journaled on said counterbalancing mechanism, a track bar fixed to the magazine and engaged by said wheel, shifter mechanism for automatically moving the selected records to and from said magazine and into and out of operative position upon said record support, shifter mechanism for automatically raising and lowering said sound box and moving the same to starting position, driving means for said record support, and said shifter mechanisms, means for initiating the operation of said driving means, and means for automatically arresting the same. 100

66. In a talking machine, the combination with a rotatable record support, and a traveling sound box, of a magazine, means movably mounting the magazine, a lever, means for pivotally mounting the lever, means engaging the lever with the magazine, a rotatable member having a plurality of cam portions engaging the lever, one corresponding to each record in the magazine, means for rotatably mounting the member, shifter mechanism for automatically moving the records to and from said magazine and into and out of operative position upon said record support, shifter mechanism for automatically raising and lowering said sound box, 120 and moving the same to starting position, driving means for said record support, said shifter mechanisms, and said rotatable member. 125

with a rotatable record support, and a traveling sound box, of a magazine, means movably mounting the magazine, a lever, means for pivotally mounting the lever, means engaging the lever with the magazine, a rotatable member having a plurality of cam portions engaging the lever, one corresponding to each record in the magazine, means for rotatably mounting the member, shifter mechanism for automatically moving the records to and from said magazine and into and out of operative position upon said record support, shifter mechanism for automatically raising and lowering said sound box, and moving the same to starting position, driving means for said record support, said shifter mechanisms, and said rotatable member, means for initiating the operation of said driving means and means for automatically arresting the same.

68. In a talking machine, the combination with a rotatable record support, driving means therefor and a suitable reproducer, of a record magazine, means for shifting said magazine to select a record comprising a rotatable shaft and connections between said shaft and said magazine, shifter mechanism for automatically moving the selected record to and from said magazine and into and out of playing position on said record support, means for driving said shaft from the driving means after a selected record has been played and returned to the magazine for shifting the magazine to select another record, manual control means for operating said shaft, and means for preventing the operation of the shaft by the manual control means when a record is out of the magazine.

69. In a talking machine, the combination with a rotatable record support, driving means therefor and a suitable reproducer, of a record magazine, means for shifting said magazine to select a record comprising a rotatable shaft and connections between said shaft and said magazine, shifter mechanism for automatically moving the selected record to and from said magazine and into and out of playing position on said record support, means for driving said shaft from the driving means after a selected record has been played and returned to the magazine for shifting the magazine to select another record, manual control means for operating said shaft, means for preventing the opera-

tion of the shaft by the manual control means when a record is out of the magazine, means for initiating the operation of said driving means, and means for automatically arresting the same.

70. In a talking machine, the combination of a rotatable turn table for supporting disc records in playing position, and a cooperating sound box, of a record magazine, means for mounting the magazine to move vertically to select a record, shifter mechanism for automatically moving the selected record to and from said holder and into and out of playing position upon said turn table, shifter mechanism for automatically raising and lowering said sound box and for moving the same to starting position, feeding mechanism for automatically shifting said magazine step by step to bring the records thereon successively into cooperative relation with said shifter mechanism, a counter-balancing mechanism associated with said magazine, an escapement mechanism, and means connecting the magazine with the escapement mechanism only when said magazine moves downwardly.

71. In a talking machine, the combination with a rotatable record support, driving means therefor, a reproducer and means causing the reproducer to cooperate with a record on said support, of a record magazine, means for shifting said magazine to select a record, shifter mechanism for automatically moving the records to and from said magazine and into and out of operative position upon the record support, an automatic mechanism for actuating the means for shifting the magazine after a record has been returned to and before a record is taken from the magazine, manual control means for operating said automatic mechanism, and means for preventing the operation of the manual control means when a record is out of the magazine.

72. In a multiple record talking machine, the combination of a magazine for supporting a plurality of records, means for swinging a record from and to said magazine, and a locking mechanism preventing displacement of the record from said means during the swinging thereof from or to the magazine.

In testimony whereof I affix my signature.

HARRY WALKER.
